UNITED STATES PATENT OFFICE.

ARTHUR M. WELLINGTON, OF NEW YORK, N. Y.; AGNES BATES WELLINGTON EXECUTRIX OF SAID ARTHUR M. WELLINGTON, DECEASED.

ART OF AND APPARATUS FOR CONVERTING HEAT INTO WORK BY AGENCY OF VAPOR PRESSURE.

SPECIFICATION forming part of Letters Patent No. 549,981, dated November 19, 1895.

Application filed February 8, 1894. Renewed April 20, 1895. Serial No. 546,530. (No model.)

To all whom it may concern:

Be it known that I, ARTHUR MELLEN WELLINGTON, a citizen of the United States, residing at New York, county of New York, and State of New York, have invented certain new and useful Improvements in the Art of Converting Heat into Work by the Agency of Vapor Pressure and Apparatus for the Same, fully described and represented in the following specification and the accompanying drawings, forming a part of the same.

The basic element of my new process lies in the dissociation of the fire or other irregular source of heat from the boiler or other pressure-generator containing the confined working substance, in order that the effective connection between the two may be secured by a heat-conveying substance which is passed from the source of heat to the pressure-generator, and which in the typical case and except for special reasons is returned to the source of heat to be reheated, so as to move in a closed cycle, being alternately heated to a desired or convenient point, passed to the pressure-generator containing the working substance, cooled to a desired or convenient point by the surrender of heat to the working substance, and returned directly or indirectly to the source of heat to be reheated. In special cases the heat-carrying substance is not returned to be reheated, but worked in open cycle, a new mass being continually received, heated, cooled, and discharged.

The heat-conveying substance I call, for convenience, the "circulating fluid," whether it be worked in closed or open cycle. It is preferably a liquid, but may be solid or gaseous in part or whole, and its sole function as a part of this process is to flow around in passage-ways which are usually endless, being preferably in continuous motion and under more or less careful regulation as to speed and temperature, and thus to convey heat to the working substance. Having such a hot fluid in motion, however, it may at times be convenient to take some heat from it for some other use, and certain gains to this process may at times result from doing so. The circulating fluid may consist either of one or of several different heat-conveying substances circulated either as a common mass or, as is often expe-

dient for practical reasons, in two or more distinct sets of passage-ways, but in either case it is spoken of collectively as the circulating fluid.

Among the cases in which it is inexpedient to use over and over a single mass of circulating fluid these two are prominent: First, in certain applications of my process a surrounding mass of air or water already heated or partially heated to the desired point by nature or in the practice of some other art may be drawn upon for the circulating fluid, and there is then an obvious practical advantage in receiving a fresh mass of circulating fluid from this existing supply instead of using a single mass over and over in closed cycle. Secondly, in all cases when fire is used for heat a continuous supply of fresh air must be taken into the heater to support combustion, and the gas thus used may most advantageously be made a part of the circulating fluid by first causing it to absorb as much as possible of otherwise rejected waste heat on its way to the heater, and then, after it has supported combustion, arranging to insure its reduction to an admissible temperature and passing it through the pressure-generator as a part of the circulating fluid, in order that it may surrender further heat before discharge. With care to insure that this gas shall be cooled down to a reasonably uniform and moderate temperature before such use, it not only may be but in large plants should be used as a part of the circulating fluid, and if so used it must be used in open cycle, even though the rest of the circulating fluid is used in closed cycle. It will be understood, therefore, that the term "circulating fluid" is intended to cover not only a fluid a single mass of which is used repeatedly, but also a fluid which is drawn from a supply utilized in transporting heat to the working substance and then voided from the mechanism.

As between air and water as a circulating fluid, each has decided theoretical advantages. Air has the very great advantage of not being changed in physical properties by any extremes of temperature, and also of being a supporter of combustion, so that when air is used as the circulating fluid the heater may be a closed chamber in which fuel is

burned in the circulating fluid itself at a regular rate, such as just to supply the heat needed to raise it to the required temperature, with a resulting large economy of fuel, 5 which in the best applications of the process may even rise to perfect economy of combustion, the gases being discharged no hotter than when received. Being eight hundred and fifteen times lighter than water, the 10 same propelling pressure will drive it about $\sqrt{815} = 28.55$ times as fast, and the friction loss will be still less in proportion, thus in a measure compensating for its lack of mass and low specific heat. For the opposite extremes of small engines, for which simplicity is an object and high economy relatively unimportant, and large engines working through a very great thermal range in order to realize 15 high economy, air alone may be a very suitable circulating medium. Air has the further great advantage in certain special applications of the process that it may be caused to change in temperature without any direct application of heat or cold simply by changing 20 its status as compressed or uncompressed. Such special applications are covered by separate applications, however, and need not be described herein. On the other hand, as a heat-transmitter, air is extremely inefficient. 25 A given heating-surface is from thirty to one hundred times as efficient between water and water and steam as between air and water or steam. Therefore a correspondingly great 30 excess of heating surface, or else of thermal head, or difference between the temperatures of the heating and the heated substances, is required if the air be used over what is required with water as a circulating fluid. Water has the great advantage of a higher 35 specific heat than any other known body, and my experiments indicate that it has also, notably, greater powers of imparting heat to metallic surfaces than any other conveniently available fluid, but it has the great disadvantage 40 of being liquid at atmospheric pressures only between zero and 100° centigrade. To overcome this deficiency by increasing the thermal range within which water is liquid, it may be circulated under pressure, and this 45 will often be expedient, though it involves certain inconveniences even when the water is used in a closed cycle and still more in open cycle. As a leading motive for using water rather than some other liquid will often 50 be to use it in open cycle, water is not an entirely desirable circulating fluid and may rarely be useful for this end at all except when its boiling-point is artificially raised by circulating it under pressure. In special 55 applications of the process water in the form of steam may serve as circulating fluid, especially when it is only a small portion of the total mass, but such use is not typical nor ordinarily expedient. 60

65 If steam were to constitute a considerable fraction of the circulating fluid, the question of how that steam should be generated would

then arise, and if it be generated in the ordinary way all the defects of practice which it is the purpose of this invention to correct 70 would still be retained. The use of steam or any other vapor condensed from gaseous to liquid state in circulation as the sole or main constituent of the circulating fluid is never expedient, and is not included within the term 75 "circulating fluid." Such a vapor condensed in circulation may, however, be used as a small part of the total mass of a circulating fluid, of which the gases of combustion form 80 a part, for the incidental purpose of producing an induced draft and to cool down the gases of combustion to a temperature approximating more closely that of the liquid circulation. There are, however, a variety of other liquids, of which paraffine-oil is an example, which remain liquid within all extremes of temperature from zero to 300° centigrade, or even more, which are chemically 85 neutral and stable, even if subjected to long-continued alternations of these temperatures, 90 which do not gum and which may be circulated with even less friction than water. They have in general a specific heat of about 0.4, which means that they must be circulated about two and one-half times as fast to supply 95 the same quantity of heat per hour to the same surfaces, and I have found them to have considerably less heat-transmitting efficiency than water when in contact with heating-surfaces; but the lower specific heat is an advantage, as it enables the fluid to be circulated faster than it otherwise could. The speed at best is slow, and on the whole these oils have most of the advantages of water, 100 with some peculiarly their own, and they constitute a convenient and suitable circulating medium when a liquid is used in a closed cycle, though requiring much more heating-surface for equal efficiency. When so used 105 in closed cycle, the scarcity or cost of the liquid does not matter, nor even its noxiousness in a free state, since no great quantity is used and there is little or no waste. There is therefore a wide range of choice in regard to the components of the circulating fluid; but, 110 so far as I yet know, either water or air or purified paraffine-oil combine the most advantages, except as follows:

As above stated, the circulating fluid may be solid in part or whole. An exclusively- 115 solid circulation in the form of a movable solid mass is a mere possibility; but it is rather the rule than the exception that a combination of solid liquid and gaseous elements gives a better circulating fluid than either 120 one or two such elements alone. Whether the base of the circulating fluid be liquid (except possibly in the case of water) or gaseous, there is generally a decided advantage 125 in mixing with it mechanically some pulverized carbonaceous or other substances of good radiating properties, while for certain extremes of both heat and cold which some of the best applications of this process require 130

no liquid known to me has the requisite physical properties, and only gases can be used.

The "working substance" to which heat is supplied by surrender from the circulating fluid may be any gaseous or liquid substance to which heat may be applied while it is confined within a chamber, with the effect of generating or increasing therein a vapor-pressure which enables the confined substance to do useful work.

In this specification and the claims all gases are considered as the vapors of liquids, whether ordinarily condensable or not. When used in connection with an engine for producing motion, the term "working substance" refers only to the substance which by its expansive pressure causes the motion, but when used more broadly and without special reference to the mechanism in which the working substance is used, the "work" to which the term is intended to refer includes any sort of useful work which may be done by vapor-pressure generated or increased by heat, whether it be working a mechanical engine or securing any other result by the surrender of part or of all of its heat or pressure.

The "dissociation" of the source of heat and working substance is simply a thermal dissociation, which may or may not be mechanical also. Ordinarily, two parts which are intended to be thermally dissociated should not be mechanically contiguous, but mechanical convenience may often render this expedient, even at some slight sacrifice of thermal dissociation. Whenever the source of heat and the working substance are so disposed that the circulating fluid may serve as the effective thermal connection between them, to the exclusion of interference by unregulated heat with the moderate and controllable action of the circulating fluid so far as is practical, the source of heat and working substance are thermally "dissociated" within the meaning of the term as used herein, although there may be some considerable residue of direct action of the one upon the other by conduction of heat through common metallic parts or otherwise.

By the apparently simple change of process above outlined we attain, or may attain, a number of highly important ends. We eliminate all temperature strains from the pressure-generator by subjecting it only to a regulated and uniform heat. We may multiply many times the efficiency of the heating-surfaces when the circulating fluid is a liquid by securing liquid instead of gaseous contact with the heating-surfaces. More important than all else, perhaps, we may radically modify for the better the functional action of the pressure-generator by applying our greatest heat at the top of the pressure-generator instead of the bottom and carrying the heating and the heated substance in opposing currents past each other, the heating substance descending as it cools, while the heated substance rises as it grows hotter, thus producing

differential temperatures within the boiler, all its materials and contents being at all times hottest at the top, coldest at the bottom, by necessary effect of the functional action, whereas in every boiler to which fire is applied directly there exists a reverse and injurious tendency and status. With a circulating fluid, also, we may permeate the entire interior of the pressure-generator with our heat-supply, the steam-space as well as the water-space. The effect of these changes in practice and in the status of the pressure-generator is too important and far-reaching to be explained in a few words or to be at once comprehended. When followed out to its legitimate results it is found to be revolutionary, both as to the theory and the practice of both steam making and steam using. The effect upon steam-boiler practice is such that the boiler practically vanishes as a factor in the bulk and cost of steam-engines, and may more accurately be conceived of as a mere enlargement of the steam-pipe in which a liquid changes into gas as it moves along. The effect upon the theory of steam-generation is to establish broadly as a general theorem that the irregular application of heat in bulk, and especially the unregulated heat of fire, to vaporizing working substance under pressure is an error of process which is destructive of economy. The effect upon the use of steam is to make possible complete new processes for the conversion of heat into work with a percentage of economy heretofore unattainable, as shown more fully in this and other applications.

This present application covers especially the improvements attained by the application of the new process of steam-generation in connection with present known processes of utilizing vapor pressure by changes based on a recognition of the fact stated above that the irregular application of heat in bulk, and especially the direct heat of fire to a confined working substance under pressure is an error of process which is destructive of economy.

While my improved process is of general application to all known types of air or vapor heat-engines, and to most other mechanisms in which heat is caused to do useful work by the generation and application of vapor pressure, it is best used, perhaps, in connection with various forms of steam-engines. The invention will, therefore, be described and illustrated with special application to steam-generation, reference being had to the accompanying drawings, forming a part of this specification, in which are illustrated diagrammatically the general features and methods of application of my process and an apparatus which I have found to be well suited for carrying out the process, the general combinations and certain specific features of which apparatus form in themselves parts of the invention.

In the drawings, Figure 1 is a diagram illustrative of the general process. Figs. 2 to 7 are diagrams illustrating various methods of

applying the process. Fig. 8 is a diagram showing in outline the general system of normal or useful and abnormal or wasteful circulation, the abnormal being shown in dotted lines and the normal with two boilers and one condenser in circuit. Fig. 9 is a drawing, also largely diagrammatic, of a substantially complete apparatus embodying the circulatory system and its adjuncts in their complete form but in the simplest case—viz., with only one boiler and no condenser in circuit, but provided with a condenser out of circuit. Fig. 10 is a detail of the expansion and supply tank constructions. Figs. 11, 12, and 13 are details of the boiler. Fig. 14 is a detail of the feeding and regulating attachments of the boiler. Fig. 15 is a detail of the valve controlling the boiler-supply. Fig. 16 is a diagrammatic vertical section of the non-circulating evaporative condenser. Fig. 17 is a detail of the grate-shaker connections. Fig. 18 is a sectional detail of the circulating-pump. Stated broadly as a general principle applicable generally to existing processes utilizing vapor-pressure, the nature of the alleged error of process above referred to, and the correction of which forms the basis of this specification, may be explained thus: Fire in large mass is an uncontrollable thing. Fluctuations of $1,000^{\circ}$ centigrade ($1,800^{\circ}$ Fahrenheit) or more may occur locally in a furnace within a few minutes or seconds of each other, and even greater fluctuations occur in the furnace as a whole at longer yet frequent intervals. This exposes all the containing-surfaces to intense and irregular alternations of extreme heat and cold. Hence the first necessity for reasonable lightness and durability is that these surfaces should be free to expand and contract *ad libitum* without doing harm. To use the other side of the same surfaces as the containing-surfaces for a mass of an explosive substance under pressure, but which yet by its conditions has a constant temperature, is illogical and absurd. It is yoking together two discordant and antagonistic things, which may possibly be done with safety, but only with costly precautions and occasional failures. These two uses of the same chamber are antagonistic and naturally require dissociation. The fire-chamber needs only the passive resistance of fire-brick, but no great strength. The steam and water chamber, if the heating as well as the heated fluid may be at sensibly constant and controlled temperatures, needs only static strength and no massiveness at all; but, on the contrary, its function demands all possible thinness and delicacy of surfaces that static strength permits. This first false step once taken—of making one what should be two—there is no resource remaining but to take several other false steps to avoid the consequences of the first. To resist the temperature strains alone, we are compelled to make the surfaces objectionably thick for heat-transmitting purposes. The direct action of fire upon them

soon gives them also a non-conducting scale or coating, which alone decreases by one-half to four-fifths their heat-transmitting capacity. Worse than all, the fierce heat impacts make it absolutely necessary that all surfaces to which they are applied shall be well immersed in water, which in turn requires that the most intense heat shall be applied at or near the bottom of the boiler and of the contained mass of liquid and shall decrease in intensity toward the top, whereas the best evaporative conditions require that it shall increase toward the top. This error in the point of applying the most intense heat in its turn insures that nearly all the steam shall be generated at the bottom of the liquid instead of at the top, and hence that it must rise through the entire mass of liquid to escape from it. Thus arises a necessity for a violent circulation, in order that fresh liquid may be continually flowing in from the side to replace that which is continually removed and carried upward from the most heated surfaces, not so much by evaporation as by the mechanical action of the rising steam. This in turn makes it absolutely necessary that there shall be within a large mass of rapidly-circulating working substance to serve as an equalizer and harmless receiver of these heat-impacts and to furnish a sufficient mass, not only to give a considerable depth of water over the heated surfaces, but also to fill certain otherwise inert side spaces for the downward circulation to which from the nature of their function heat must not be applied, and which, therefore, only serve to increase the bulk of the boiler and working substance without adding to the evaporation. It is true that the large mass of contained working substance thus enforced has the slight additional use of giving a small store of reserve power which may be drawn on for a few moments; but that function, also, is better subserved otherwise. This large quantity of functionally useless and inactive working substance makes the boiler a magazine of explosive energy and so necessitates still greater strength, not for ordinary needs, but for rare emergencies, which exist only because of the uncontrolled and intense heat-impacts. Under my process, when best applied, I rarely need so much as one per cent. of the usual mass of working substance. This need for rapid circulation of a great mass of liquid in its turn requires that the active heating-surfaces shall be widely spaced with large free intervals between them for circulation, and this in its turn, with the requirement that all parts shall be of massive strength, forbids the production of any large amount of heating-surface in a small space, and hence requires that what heating-surface there is shall be intensely active and the ebullition from it intense and violent. This in its turn demands that the external thermal head shall be large, and hence that much heat shall be discharged to waste, and also insures internally such violent upward foaming from the most heated

spots that a large amount of priming must result, and this last in its turn requires a large and otherwise useless steam-space above the seething water, in order that in its comparative quiet some of this water may drop back again out of the steam. Naturally much of it refuses to drop back, but remains in the steam. Again, the intense and irregular heats used forbid our exposing this steam to further heating-surface to evaporate its entrained water and superheat the steam. The gases must be discharged to waste still highly heated for the very reason that they are so highly and irregularly heated, while the steam cools in its steam-space rather than is heated, that being the coldest part of the boiler, whereas it should be the hottest. Again, returning to the fire, in order that the concentrated impacts of heat may not be absolutely destructive, it is necessary to spread out the fire over a large area, fire it with great care and skill, and leave large and to a great extent otherwise needless vacant spaces above and around the fire to prevent too fierce attack by it upon the working substance, further increasing bulk and massiveness.

So I might go on and trace the calamitous effect of the basic error stated through the entire mechanism, especially in connection with the prevalent idea that water is the only convenient, or a specially convenient, working substance, which is certainly sound enough under present conditions of practice, and under any conditions for non-condensing engines, but which has no other logical foundation for condensing-engines when traced back to its starting point than the basic error referred to. It is believed that, in the light of a larger knowledge and at no distant day, these methods will be looked back upon with wonder as needlessly barbaric, absurd, and crude—as much so, both in nature and degree, as the old Newcomen process of using the same chamber both as a working engine and a condenser. In fact, the modification of process covered by this application bears a close analogy to that by which the modern steam-engine process was evolved from the Newcomen or pre-Watt process, each consisting simply in a differentiation of process by which additional steps are introduced to effect the same result. The essentials of the respective basic processes may thus be stated:

The old pre-Watt process employed three elements: first, a furnace and boiler combined; second, a passage for working substance, and, third, a working engine and condenser combined. Watt, in 1769, differentiated this process by separating the engine and condenser, and thus increased the conversion efficiency of the steam from one per cent. to about five per cent., which one hundred and twenty-five years of effort in perfecting details has since expanded to a maximum efficiency of about fifteen per cent. The process thus obtained and still in universal use employs the following elements: first, a furnace

and boiler combined; second, a passage for working substance; third, a working engine; fourth, a passage for the exhaust; fifth, a condenser voiding combined heat and working substance externally. In the process of forming the present invention, however, this Watt process is differentiated still further by separating the furnace and boiler, as illustrated in the diagram Fig. 1 of the drawings, accompanying this specification and employing the following seven elements: first, a heater H; second, a passage V for circulating fluid from heater to boiler, and preferably, also, for return to boiler; third, a boiler B to which no fire is applied; fourth, a passage P from boiler to engine; fifth, a working-engine E; sixth, a passage P' for the exhaust; seventh, a condenser C.

It is obvious that this process, as well as the pre-Watt and Watt processes may be abbreviated at the expense of economy by omitting the condensing step. The two latter processes then become identical, each alike giving the modern non-condensing-engine process, but the pre-Watt process never was, in fact, so abbreviated.

Before describing the details of my new process I will describe the general method of applying it to existing forms of steam-engines and the advantages which result therefrom.

I will take the locomotive as one of the most unpromising examples of modern engines for a modification of process. I will regard and treat its two engines as one, that making the case still less favorable. Let, then, all fire be removed from the fire-box and placed in a separate receptacle, say on the tender. Let the grate be closed and made water-tight. Let suitable baffle-plates be put into the abandoned fire-box and at the ends of the tubes, so as to promote an effective circulation, and let the first and greatest heat be applied at the top of the boiler and not the bottom. Let hot paraffine-oil or hot water under pressure be circulated from the fire-box through the boiler as the boiler's source of heat, and by suitable regulating appliances, manual or automatic, let the oil be heated to some approximately fixed point—say to 355° centigrade (671° Fahrenheit)—and cooled before returning to the heater down to the boiler-temperature or any desired point above it. Let the engine be working high pressure, as usual, between 100° and 185° centigrade, (212° and 365° Fahrenheit,) corresponding to steam at 11.2 and one atmosphere (one hundred and sixty-four pounds and 14.7 pounds per square inch) absolute pressure. These conditions only require that the mass per stroke of the circulating fluid shall be about 3.87 times the mass of water evaporated per stroke, (or 9.68 times for specific heat 0.4,) implying an almost imperceptible speed of circulation. Fig. 2 of the drawings shows to a rude vertical scale of temperature the thermal conditions then obtaining, in which H is the heater on the tender and a the engine work-

ing non-condensing between T' and T'' . The arrows show the path of the circulating fluid, which merely serves to convey heat to the steam, not to bring any exhaust heat back. 5 At the temperature and point T the circulating fluid enters the boilers, is therein cooled through 255° centigrade down to the steam-temperature, and then returns back to the heater to be heated up again to T . It is now 10 easily seen that we have thereby enormously increased the thermal efficiency of the boiler. A liquid at 355° centigrade (671° Fahrenheit) is in contact with every part of the fire-box and tubes, this being hotter than the most 15 exposed points of the inner face of the fire-box ever are with radiant heat at $1,500^{\circ}$ to $2,000^{\circ}$ centigrade ($2,732^{\circ}$ to $3,632^{\circ}$ Fahrenheit) acting directly upon them, as shown by the fact that lead safety-plugs melting con- 20 siderably below 355° centigrade (671° Fahrenheit) do not melt in it; but every part of the heating-surface, both fire-box and tubes, now 25 is or may be exposed to this same temperature and liquid contact. As illustrated in Fig. 2, the mean thermal head for the whole heating-surface is only half as great as this; but as hot water or oil is from twenty to fifty times as effective a heating medium as air with a given surface and a given transmission inter- 30 val we have then an enormous surplus of heating-power. Our greatest heat being applied at the top, our greatest steam-generation is there, and there is no longer either necessity for or tendency to interior circulation; but 35 our metal surfaces may now be bright instead of dull, again greatly increasing their heat-transmitting capacity. We may also run heating tubes through our steam-space, and thus not only dry, but highly superheat our 40 steam. We have no longer any sensible temperature strains. We can dispense with nearly all of the water in the boiler, which has been put there only to receive and equalize heat impacts which no longer exist and 45 to maintain a circulation which no longer is needed. Both for this reason and because of our enormous excess of heat supply, we can make our boiler much smaller. We also need no extra thickness as a guard against explosions. We can also use much thinner and smaller tubes, and so reduce our boiler still 50 smaller. We need no longer any space whatever for the fire-box. The superheating of the steam alone, which is a natural result of 55 the above process of steam-generation, is likely to reduce greatly or even avoid altogether the customary excess of thirty to fifty per cent. in actual steam consumption over what the indicator-cards call for. Every con- 60 dition is improved. Our heater on the tender also works under improved conditions. The grate and its containing-box may be smaller and the fire correspondingly deeper. It may be contained in a plain iron box, which 65 does not attempt to resist temperature strains and so does not deteriorate under them. The surrounding liquid is below its boiling-point.

Consequently it generates no steam, and consequently we may use for it any kind of cheap metallic surfaces which may safely be brought quite close to the fire. The gases of combustion may be carried in close contact with these metallic surfaces and their extension for some distance at the cool end, and thus be much cooled down before discharged. The irregularities of temperature which necessarily result from using the same surfaces alternately and irregularly for heating, evaporating, and superheating, with their very different rates of heat absorption, no longer exist, while the irregular heat impacts which we cannot avoid in a fire-box do no harm to such surfaces as described, which are free to expand and contract. Our exhaust-steam may still be used to cause artificial draft; but by placing a thermostat in the circulating fluid we may regulate precisely the air-supply which we allow to enter the fire, so as to produce just enough heat and no more—a method of regulation which we cannot use when the heated substance is the steam-producing liquid itself, which does not change in temperature with the quantity of heat supplied after its working pressure has once been reached.

It will now be obvious, also, that having greatly reduced the necessary size of our boiler we may move back our heater from the tender to its usual place on the engine and still preserve all the conditions with the heater on the tender. The dissociation of boiler and fire-box, as above explained, refers only to thermal conditions and does not forbid that they be mechanically contiguous. We have simply to cut off the present fire-box and its heating-surface bodily, put a much smaller plain box for a heater in its place and we still have left, in the barrel of the boiler only, many times more steam-space and heating-surface than we have any use for. Therefore reducing our boiler to its required dimensions only we have plenty of spare space and weight for an air-cooler or a condenser if we choose to add one. All this has been accomplished under the most unfavorable conditions, allowing for only one engine. With two or more engines to run we can do much better in a variety of ways, as illustrated in Figs. 3 to 7 of the drawings, and as will be explained hereinafter.

The preceding is regarded as sufficient to establish the generality of the principle that the new process as applied to steam generation by introducing a circulating fluid as the thermal connection between fire and boiler is a direct advantage to the simplest engine processes, in addition to opening an easy road to further and greater modifications of process.

I now proceed to describe the details of the process more precisely, since its advantages only have been so far explained, and not its limitations. A circulating fluid cannot be used without great sacrifice of its possible advantages, except in connection with certain

regulatory and other adjuncts so far unconsidered.

In the first place, if the circulating fluid be a liquid, an expansion-tank or its equivalent must be used, since all fluids expand when heated with irresistible force, and since the circulating-pipes should at all times be full of fluid, and yet not more than full. It is then theoretically possible by providing circulating-passages of immense strength, such as can resist any extreme of vapor-pressure which any fire can create and by substituting great vigilance for automatic regulation, to circulate a heat-conveying liquid between an ordinary unregulated fire and an ordinary type of boiler and realize some of the advantages which have been described; but for practical results from the process, except, possibly, in special applications not forming a part of the invention covered by the present application, whether the circulating-fluid be a liquid or a gas, it must include one or more of the following features, and to realize its highest advantages it should include them all. These adjuncts are arranged in their logical sequence in the process.

A. Regulation of the maximum temperature of the circulating fluid—that is, the temperature of the circulating fluid as it passes to the boiler.

B. Regulation of the volume of the circulating fluid so as to keep it sensibly constant at all temperatures.

C. Application of the circulating fluid to the working substance in such a manner as to produce and utilize differential temperatures within the boiler, as below explained.

D. Regulation of the minimum temperature of the circulating fluid—that is, the temperature to which the circulating fluid is cooled in the boiler—preferably by controlling the speed of circulation.

E. Regulation of the volume of working substance in the boiler so as to keep it sensibly constant.

F. Regulation of the degree of pressure which can exist in the boiler.

Most of these adjuncts may be quite simply effected, and by different means. The appliances which, as a rule, I deem preferable are given below; but I limit myself to no particular form of these appliances, as the process may be adapted to the use of many different forms. I proceed to consider them in order.

Adjunct A.—Regulation of the Maximum Temperature of the Circulating Fluid.

By this I mean the regulation of the temperature of the circulating fluid on the hot side—that is, as it passes to the boiler or boilers—which is its maximum. This is the most essential element in respect to safety of the apparatus when the fluid is heated by the direct action of fire. Otherwise all the passages must be of immense strength and thickness, since the volume of the circulating fluid is

small, and its capacity for absorbing heat also small, because of the lack of any vaporization. Therefore without regulation of the temperature imparted the pressure within the pipes is liable to rise at any time when rapid withdrawal of heat ceases very nearly to that due to the temperature of combustion, which is several hundred atmospheres with any probable circulating fluid. Of course any danger of explosion from such pressure may be guarded against by a suitable safety-valve, which in any case should be added as an additional precaution; but this involves loss of fluid from the circulating-pipes, and consequent disabling of the apparatus. It should exist only as an additional and independent precaution, which is very rarely called into action, and never in normal working. The only proper normal method of regulation is that the rate of imparting heat to the circulating fluid shall instantly decrease when the temperature or pressure within it reaches a certain point. Various methods of securing this result may be used, and it matters not what particular method be chosen, and each may be brought into action either by the temperature or by the pressure of the circulating fluid through appropriate thermostats, valves, or diaphragms. I confine myself to no particular method; but one or more attachments for this purpose are preferably used in all cases, and should come into action before the circulating pressures reach such a point as to open the circulation safety-valve. This becomes especially important when the circulating fluid is water circulated under pressure to raise its boiling-point, as above described, and in most cases it is likely to be thus circulated under heavy pressures, if used at all, in order to get a large thermal head or a greater thermal range.

For the regulation of the maximum temperature of the circulating fluid three general methods are possible, which are independent of each other and may be effected by different means, and which, preferably, are all used. These are, first, regulation of the air-supply; second, regulation of the fuel-supply, and, third, waste of heat after combustion. These will be considered in order.

Regulation of air-supply.—Inasmuch as the circulating fluid can practically store no heat, nor the boiler, either, when properly designed, as will be seen hereinafter, the main reliance for economical combustion must be on direct control of the rate of combustion through the air-supply or the fuel-supply, or preferably both.

The air-supply can be regulated automatically with great exactitude by making the heater perfectly air-tight, or as nearly so as may be, and providing two openings for air-supply, one of which admits air below the grate to support combustion and the other of which admits air above the grate in part to perfect combustion to the extent that the nature of the fuel makes necessary, but

chiefly to check combustion when necessary, by admitting air above the fire so as to destroy the draft through it, as well as to cool the gases of combustion. To this end the opening below the grate should be of such size as to admit all the air needed for good combustion at the most rapid rate when full open, and no more. It should be controlled by any simple valve, preferably a plain flap-valve, which 10 closes completely when the temperature or pressure of the circulation reaches a desired working maximum, and this should be the first regulatory adjunct to act. The opening or openings above the grate should also be 15 controlled by some flap or other valve which never closes the opening completely if air above the fire is a necessity for good combustion, but which otherwise may be normally closed. Before heat begins to be wasted, as 20 hereinafter described, however, this valve should open pretty widely, since it has the double effect of checking the production of heat, as well as getting rid of it wastefully, and thus is more economical.

25 *Regulation of fuel-supply.*—With any form of liquid, gaseous, or pulverized solid fuel this is very easily effected by a valve acting concurrently with that controlling the air-supply for combustion. It should, therefore, 30 in most cases be mechanically a part of the air-supply valve, and in all cases may and should be actuated by a common regulative connection, so as to be synchronous in its action. I contemplate the use of such gaseous 35 or pulverized fuel so far as possible, for the very reason that the supply is so easily regulated. When coal in solid form is used as fuel, such direct regulation is not possible but in practical effect it may be closely approached. I recommend in all cases that the 40 grate be given an adjustable and automatic slow rocking or rotating motion, so that the fires may keep themselves in good order with a minimum of attention. It is far more important to do this than with the now usual processes of steam generation. These last are carried on under such dangerous and unfavorable conditions at best that constant skilled attention is required anyway. My aim in developing this process has been to utilize to the 45 fullest extent its inherent advantage of being naturally safe and self-regulative. Therefore I recommend not only that this mechanical rotating or rocking action of the grate be 50 always obtained, which may be done by a suitable connection from any moving part, but that it be made automatically variable according to the temperature or pressure of the circulating fluid, preferably by a connection 55 with the same regulator which controls the air-supply, in such a manner that all grate motion ceases, or at least is diminished, whenever the circulating temperatures begin to rise above the desired maximum. It is easier 60 to stop the motion altogether than merely to diminish it, since the first requires only some simple disconnecting device actuated

by the thermostat or pressure device while the second requires a change of some leverage. Therefore instead of aiming at a continuous though variable movement the motion should for convenience be intermittent, but comparatively vigorous when it occurs. It should in any case be slow, however, in order to give its effect time to show in the 70 temperatures before it goes too far. This regulatory adjunct becomes especially desirable when the fuel used is anthracite. In that case the "base-burner" principle, under which the fire is fed continuously by a magazine of fuel above it, will ordinarily give the best results, and if this be combined with regulated movement of the grate the fire may be kept for many hours together in just the condition required by the demand for heat, 75 whether regular or irregular, without any further attention than to insure that the fuel-magazine is not exhausted.

Waste of heat after combustion.—There are four obvious efficient ways of effecting this 80 end, all of which may be used, and which are preferably brought into action in the following order: First, opening a direct escape for the gases of combustion so that their heat is wasted; second, passing the circulating fluid 85 through a wasteful cooler after it leaves the heater; third, a temperature safety-valve positively opened; fourth, a pressure safety-valve opened by excess of pressure. All these methods are wasteful, since they merely discharge to waste the excessive heat of combustion, which otherwise would be imparted to or remain in the circulating fluid. They should, therefore, not be the primary reliance for heat regulation any more than the safety- 90 valve, though they may be made so by sufficient care in firing; but the regulative methods previously described, which are a check upon the actual generation of heat, are preferably used in all cases, whether with or without 95 any or all of these wasteful methods. The opening of an escape for the gases of combustion may be secured by a damper of any common form actuated by any suitable means, such as a thermostat, and the temperature 100 safety-valve may be placed in any suitable position upon the circulating system and operated by any similar means. Any common or suitable form of pressure safety-valve may be 105 used.

The wasteful cooling of the circulating fluid after it leaves the heater may best be secured by an open evaporative tank, into which the circulating fluid is directed from the normal circulating system when the temperature rises 110 too high, so that the temperature of the circulating fluid in the boiler may at once be reduced independently of any lessening of the amount of heat imparted thereto. This change of the circulation is preferably controlled automatically by means coming into effect before the safety-valves, but after the other regulative means above stated, so as to act in 115 case any of them should fail or all prove in-

sufficient; but it is preferably controlled manually also, the special and most important function of this feature being to cut off at once the circulating fluid from the boiler when the boiler system is thrown out of operation, and it is then desirable that this should be done by hand at once and independently of any other regulative appliance. In fact, deflecting the circulation into this wasteful cooler is one of the best ways of stopping the engine when there is no special haste to do so, since it has the further advantage of relieving the boiler and heater of all sudden increase of temperatures. This change of the circulation is indicated in Fig. 8, which shows in diagram the complete circulating system with two boilers and a condenser in circuit. Under the arrangement shown, engine E is a condensing-engine working between the boiler B and condenser C, while E' is or may be a non-condensing engine discharging its exhaust into the atmosphere. So far as the circulating system is concerned, it is indifferent whether E' is non-condensing or whether it has a condenser not in circuit, served by some external cooling agent. To make the circulating system of Fig. 8 conform to that of a single boiler, it is only necessary to omit boiler B' and condenser C and their connections and run pipe V' directly from the lower part of boiler B to the heater H.

The normal circulation is shown in Fig. 8 by the parts in full lines, and is from the heater H, through the pipe V, to the expansion-tank T, and thence through the second pipe V to the boiler B. After circulating through this, as shown by dotted lines, the circulating fluid passes by the pipe V to and through the second boiler B', which may ordinarily contain some more volatile working substance than boiler B. In any case, the circulating fluid is considerably cooled by passing through the boiler B', and thus is fitted to return through a condenser C, which receives and condenses the exhaust-steam from the engine E, served by the boiler B, and to absorb and return to heater some fraction of the otherwise wasted heat of engine E. From the condenser C the circulating fluid returns through the pipe V' to the heater H, to be reheated and repeat its circuit. The abnormal circulation is shown by the parts in dotted lines and is brought into action by shifting three-way cock x, when the boilers are cut out of the circulation and the circulating fluid passes from the tank T, through the pipe V² and open evaporative tank Z, back to the heater. This abnormal circulation comes into action temporarily only for the brief periods in which withdrawal of heat through the boilers has ceased while there has not yet been time to stop the generation of heat in the heater, so that the excess must be dissipated unless the internal temperatures of the system are to increase objectionably. Whenever gaseous, liquid, or pulverized solid fuel is used, this abnormal circulating system becomes unne-

cessary, because in that case the generation of heat can be stopped as suddenly as its withdrawal. There is another method by which this wasteful regulation may be attained—viz., diverting the circulating fluid, or a part of it, from the heater, or from the hottest part of the heater—but on account of obvious mechanical and economical difficulties, and especially the importance of protecting all parts of the heater against overheating, it will probably not be found desirable to use it.

It is obvious that many different means may be used for securing regulation of the maximum temperature by some or all of the methods above pointed out and that either thermostatic or pressure regulation may be used. As between thermostatic and pressure regulation, however, I prefer the former, since a thermostat may be made so simple, and yet so positive and certain in its action. Which ever be used, however, we may, by a single thermostat or regulator, control all the following regulative features so as to act at successive small increments of temperature or pressure: first, decrease the fuel supply or stop the grate-shaker; second, shut off air supply below grate; third, admit air above grate; fourth, discharge hot gases wastefully; fifth, divert the circulating fluid into an evaporative pan for wasting heat; sixth, open positively some relief-valve. It is better that the positive action of a proper thermostat should be relied on to open a safety-valve rather than internal pressure, because the thermostat acts or may act with practically resistless power, while it is almost impossible for it to get out of order. Nevertheless, as it is conceivable that it might fail, an independent pressure safety-valve of the usual type should be added. By these six methods, together with a pressure safety-valve, we may have perfect regulation of maximum temperatures, and at all times in the most economical way which is adequate for the needs of the moment. As they are all so simply attained, there is no motive for omitting any one of them. Nevertheless, as each one of them is independently effective, any one or more of them may be used without the others, and with a little more care and risk may be sufficiently effective and but little more wasteful.

Adjunct B.—Regulation of Volume of Circulating Fluid.

The circulation may be effected in part by the natural action of the difference in gravity of hot and cold fluids, as outlined in Fig. 8, where the expansion-tank T is at the top of the system and the heater H at the bottom. By an old and well-known process it is only necessary that the expansion-tank shall thus be the highest point on the system and the heater the lowest or nearly the lowest, to have quite a rapid natural circulation begin under the conditions sketched, and continue so long as heat is supplied in H and abstracted in some considerable quantities in B or else-

where on the circuit IIV TV BV BV' CV' H. The rapidity of natural circulation may be increased by elevating the boilers and tank T, and this natural circulation alone may 5 nearly or quite suffice if the circulating-passages be made large enough; but for reasons given more fully below a high speed through small passages gives better evaporative duty than a low speed through large passages, and 10 hence a circulating-pump is nearly always expedient even with only one boiler in circuit, and still more when there are several boilers and, perhaps, several condensers also. If the 15 expansion-tank has only a moderate elevation, the circulation will be purely liquid only so long as the liquid in the tank T stands at or near to the level of the hot intake. Thereafter unless there be a circulating-pump and the engine is in motion it will only be continued 20 by the generation of steam in the heater, which is objectionable because no metal surfaces exposed to the direct action of fire should be alternately bare and in contact with liquid. Therefore it is desirable that 25 the circulating fluid shall at all times be maintained in a nearly-constant volume, and this in starting the fires as well as when working, though this latter is not so important. Under these circumstances when a moderate 30 range only is contemplated, as from zero to 100° centigrade or less, as in most hot-water heating-plants, it is sufficient to fill a small-sized tight drum about half full and rely on occasional inspection to maintain the proper 35 height of liquid within it. The change in the volume of water for such a range is only about four per cent; but when temperatures as high as 400° centigrade (752° Fahrenheit) or more are contemplated the change in volume 40 is greatly more than in proportion, being nearly one-third, and, moreover, most of the oils expand with heat about twice as much as water, so that a very great change of volume must then be provided for. This may be done 45 either by using a very large expansion-tank or by providing means for regulating with some exactitude the level of liquid within it. If the first expedient be resorted to, the tank should have for water an interior volume of 50 about two-thirds of the total volume of the liquid circulation in order that there may be some liquid in the tank when it is coldest, and that it may not be more than half full when it is hottest. This is the simplest expedient, 55 and in order that it may be feasible it is desirable that the volume of the circulating fluid should be kept at its minimum by using no unnecessary lengths or sizes of circulating-passages; but the expansion-tank may be 60 made much smaller and the volume of circulating fluid kept constant regardless of temperature or oversight, which is highly desirable, by providing a separate storage-tank of ample capacity, which yet need not be great, at 65 some convenient point, preferably higher than the expansion-tank, and connecting it therewith in such manner that when the ex-

pansion-tank is more than about half full liquid flows from it to the storage-tank, and when it is less than half full liquid flows into it from the storage-tank. This may best be effected by having inside the expansion-tank a float of some considerable size and power, which floats about half immersed, so that it may act with about equal effect by its gravity 75 downward or by its flotation upward. When the liquid falls too low, this float opens a valve which equalizes steam-pressure between the expansion and storage tanks, and so permits liquid to flow by gravity or otherwise from 80 the latter to the former through a pipe connection between the bottoms of the two tanks, which pipe should be provided with a check-valve against any undesired return-current. After sufficient liquid has thus been admitted 85 the float will rise and close the valve, leaving the steam admitted to the storage-tank to condense therein by natural radiation, either producing a vacuum or restoring atmospheric pressure, as desired. If the liquid rises too 90 high, it can only do so because it is expanding from heat, which means that there is or always may be, by having a trifling percentage of some more volatile ingredient in the circulating fluid, some small pressure, at least, 95 in the expansion-tank. Therefore all that the float need do is to open a valve in the bottom, which closes a pipe leading to the storage-tank, and the internal pressure will drive the surplus liquid out directly. Both of these 100 valves may and should be quite small, since the changes of volume should take place quite slowly. Therefore the work thrown on the float is very light, so light that the float may be entirely dispensed with and the gravity of 105 the contained liquid alone used to actuate the valves, by making them sufficiently delicate; but this would be inexpedient. Temperatures or pressures cannot be used to effect this regulation for obvious reasons; but the mechanical details may be greatly varied. I attach 110 considerable importance to this regulative adjunct. To use the process in the best way we must deal with high-liquid temperatures, implying great changes of liquid volume. 115 By the aid of this adjunct, nevertheless, we may use quite a small expansion-tank. We may be sure that it is just full enough and not too full under all conditions and without any manual regulation, and we may put the 120 storage-tank at any distance we please from the expansion-tank, connecting the two by two small pipes, so that it will not be in the way. It is not even necessary, though it will usually be expedient, that the storage-tank 125 shall be higher than the expansion-tank, since some slight and constant pressure may be substituted for gravity.

Adjunct C.—Boiler Process.

A circulating fluid which is otherwise properly handled may be used with great advantage with any kind of boiler, as we have seen, since we may leave the boiler otherwise the

same and get improved conditions for steam generation and a far greater steam-supplying capacity without other mechanical change than substituting a circulating fluid for fire as the heating agent. As above stated, however, the circulating fluid should be applied, first, to the hotter parts and then to the colder parts of the working substance, being passed downward from top to bottom of the pressure-generator, instead of applying the heat first to the bottom of the working substance, as at present. The difference between the two cases and the proper functional management of the circulating fluid may be most clearly shown by taking a simple type of boiler originally designed for fire—say a vertical tubular—though it matters not what type be chosen and showing how such a boiler may best be adapted to the use of a circulating fluid. Expressed in the fewest possible words, the proper method is to enter the circulating fluid hot through the passage which before was the uptake or chimney, and then pass it downward through the tubes in which the gases before went upward, whence it goes much cooled into the fire-box which was before the source of heat, and thence out through the grate, thus directly reversing the usual currents and comparative temperatures. In every sort of boiler the circulating fluid should enter at the top, thence work its way down, more or less circuitously, and pass out cooled at the bottom. In the vertical tubular boiler this descent is direct through passages which already occupy both the steam-space and the water-space. In a horizontal tubular boiler the descent is properly in horizontal zigzags, and there are no tubes in the steam-space, which should accordingly be added for the best results. In either case the need for circulation has vanished and the tendency to circulation has been largely reduced. The need for circulation resulted only from the intense heats of the fire and the generation of most of the steam at the bottom of the boiler. The tendency to circulation has been decreased, as the most of the steam is now generated near the top and none near the bottom, thus avoiding largely the mechanical action of the rising steam. Some tendency to circulation still remains, however, owing to the unequal distribution of heat in different parts of the boiler, which is increased largely by the side spaces left cold intentionally to provide passages for downward circulation. It is important that all tendency to circulation be eliminated and circulation prevented, and I secure this result by the uniform distribution and close spacing of the heating-surfaces. By “uniform distribution” is meant such distribution of the heating-surfaces that all of the vertical columns into which the water in the boiler may be conceived to be divided between such heating-surfaces and between the heating-surfaces and the boiler-shell shall receive substantially the same amount of heat and be of the same mean temperature and density

and no cold spaces be left for downward circulation, as in the boilers now in use. The distribution of the space between the heating-surfaces and between the heating-surfaces and boiler-shell will depend upon the nature and size of the heating-surfaces employed. If tubes be used and they are of the same size throughout the boiler, the spacing will be equal, but the spacing may and preferably should increase somewhat with the size of the tubes, if different-sized tubes be used. By “closely spaced” is meant that the heating-surfaces must be spaced at such distances apart as to avoid the formation of any cold interspaces through which downward circulation may be set up. If tubes be used, the requisite spacing will depend somewhat upon their size and the intensity of the heating action, the smaller the tubes and the lower the intensity the closer the spacing required. The effect of this construction is that the water is at differential temperatures and densities throughout in horizontal layers, lightest at the top and heaviest at the bottom, and therefore actively resists and prevents any circulation which the steam generation might otherwise cause. This being the case, it will be easily seen why any type of fire-boiler is needlessly bulky and clumsy for use with circulating fluids, and why the continued use of such types would involve great and needless sacrifice. In the first place, as we have no need to provide for circulation, and as our heating-surfaces never rise above or fall below an externally-fixed temperature, we neither gain nor lose dynamically by having more liquid in the boiler than is needed to give the desired area of liquid contact with our heating-surfaces. As we gain a mechanical advantage by reducing the contained quantities we should do so. We need no large liquid mass to receive irregular heat impacts, because we have none. We need none to prevent excessive steam generation at particular points or moments, because our steam generation, if excessive, is continuously and uniformly so and not affected by interior volume, so that it must be controlled in other ways. As no interior circulation is wanted and none will occur, however widely spaced the tubes, within the limits defined we need no wide spacing of tubes. Therefore the tubes may be and preferably are very closely spaced whatever their size, and no more liquid than is needed to give contact with them need be inclosed. There is indeed one small advantage from having a large volume of contained liquid, that it serves in some degree as a reserve of power; but this end is better attained ordinarily by the thermostatic regulation of the fires. As economy requires that they be not pushed very hard in regular working, they will respond instantly and automatically to a considerable extra demand under the conditions of this process. A still more important end is or may be secured by the construction explained, which carries the

heating and heated substances in opposing currents past each other, and so introduces differential temperatures within the chamber—viz., that it reduces the necessary mean thermal head. This feature becomes of much importance in certain processes referred in other applications and is there more fully explained; but the tubes no longer need to be large or thick to let gases of combustion through freely or to resist temperature strains or abrasion of cinders. Therefore they should be quite small, since the liquid at slow speed flows through small tubes equally well and the weight of the tubes per square foot of surface varies directly with the diameter and the heating area per cubic foot of boiler inversely therewith. Therefore we need twice as large and heavy a boiler with one-half-inch tubes as we do with one-fourth inch, and proportionately for other diameters. With two-inch tubes the boiler is increased eightfold over one-fourth-inch tubes. It is even then so small that the larger sizes may often be usefully employed, and perhaps longer experience will indicate that larger tubes than I now favor are preferable; but so far as I yet know one-fourth-inch copper tubes are more suitable for any size of boilers than larger tubes. With tubes of this size the boiler may be, as already stated, so small that it may more properly be considered as a mere enlargement of the feed-pipe in which water is turned into steam as it moves along by passing between evenly hot surfaces at a fixed rate, since as much as one-hundred horse-power of steam-power may be continuously and economically produced per cubic foot of total boiler volume, as shown more fully hereinafter among mechanical details. Nevertheless it will often be inexpedient to attempt such very high duty, for reasons explained at the close of the description of the next adjunct—D. It follows from these facts that the boiler-surfaces need not be tubes at all. I do not confine myself to them. They may instead be a mass of thin flat plates closely spaced and indented or corrugated, so as to keep their spacing against whichever fluid is under the greatest pressure, whether the circulating or the working substance. Such a boiler is fully described and claimed in another application, Serial No. 507,258, filed April 12, 1894. In any case the boiler will ordinarily give the best results when from two-thirds to four-fifths full of liquid, and it is better to have a considerable area of heating-surface, perhaps ten to fifteen percent. of the whole, devoted to superheating uses alone. The possibility of very highly superheating without risk or any special appliances therefor is one of the greatest advantages of the use of my process.

As we have no need for any steam-space beyond what is required for generating and superheating the steam, it follows from all that has preceded that the best boiler for use with a circulating fluid will consist of a mass of thin and delicate heating-surfaces filling

“steam-space” and “water-space” alike without any distinction between them, with no greater total bulk than is needed to insure enough heating-surface, with the circulating fluid entering hot at the top and working its way downward to the bottom, and with the working substance entering cold at the bottom and leaving hot at the top. Other details may be varied at pleasure within wide limits, as also the character of the heating-surfaces; but the character and arrangement of surfaces described will be found to secure many advantages. 80

The principle that heat applied to a vaporizing substance under pressure should always be most intense at the top and coldest at the bottom is one of general application, and the mere correction of this error, with a minimum of other change, will always result in improved functional action, all the present commercial forms of boilers violating this principle. The broad basis for this principle lies in the fact that inasmuch as all possible working substances expand with heat and contract with cold gravity always tends to segregate the exterior mass of working or heated substance into horizontal layers, coldest at the bottom and hottest at the top, and when the process of heating produces and includes a change from the liquid to the gaseous form this tendency to segregation is of course vastly increased and becomes irresistible by any violence of circulation. Therefore, in order to produce the smoothest and most efficient action of a boiler the heating agent, whatever it is, should act first at the top with its greatest intensity of heat and then pass from the top downward, or in a reverse direction, to the heated substance, which should enter cold at the bottom and leave hot at the top. The heating agent thus first superheats, then renders heat with great intensity and rapidity for vaporization, which confines that process chiefly to the immediate vicinity of the surface, its intensity decreasing directly with the depth below the surface until at one-fifth to one-half of the total depth of liquid vaporization practically ceases. Only when the working substance is fed at the boiling-point will it extend through the entire depth, and then its intensity will decrease with the depth, so that three-fourths of it will occur in the upper half of the liquid. The heating agent having passed below this depth, all the remainder of the liquid is still below the boiling-point, and hence more efficient than it otherwise could be for abstracting heat from the now much-cooled heating agent, and hence the latter is cooled before it is discharged, sensibly, below the point possible, when, as in most present types of boilers, most of the gases never encounter any liquid below the boiling-point before discharge. 130 Heat from whatever source and however communicated should always be supplied to a pressure-generator first and hottest at the top, and thence should be decreased in intensity

by being passed downward, cooling as it goes, and my improved boiler process and boiler for applying this principle form in themselves parts of the invention, although they are preferably used in a system employing the other features of the invention. A boiler or pressure-generator designed according to these methods is a reversible mechanism—that is to say, it is only necessary to reverse the direction of the two currents of heating and heated substance which pass through, all temperatures and pressures remaining the same—and it becomes an equally efficient condenser or cooler of the vapor which before it generated. 15 This results from the fact that the real aim in both cases is the same—that is, to transfer heat from one substance to another. Hence, for reasons already given, the substance which is to surrender heat should in each case enter 20 at or near the top and go out at or near the bottom, while the substance which is to absorb heat should enter at or near the bottom and go out at or near the top. When the chamber is being worked as a boiler, the working substance is to absorb heat and enters as a liquid from the bottom, going out as a vapor at the top. When the same chamber is to be worked as a condenser for the same vapor, the working substance is to surrender 25 heat, and hence enters as steam at the top and goes out at the bottom. The heating agent in each case alike flows in the reverse direction to the working substance, its proper top and bottom temperatures remaining the same. 30 Ordinarily the vapor which we wish to condense is not in quite the same status as the steam which we wish to generate, and some slight mechanical difference may result from this fact; but this is another issue and so 35 40 small a one in all ordinary cases that a well-designed boiler and condenser should be mere duplicates of each other, despite the differences of pressure.

My improved process of condensing or cooling a vapor depending upon the correct application of the principles above stated is of general application independently of the other features of the invention, and this process forms in itself a part of the invention, and it 45 50 will be understood that an apparatus for transferring heat from one substance to another, constructed as described and claimed, forms a part of the invention, broadly considered, whether used for the purpose of generating vapor pressure or for condensing.

Adjunct D.—Regulation of Minimum Temperature of Circulating Fluid.

By this I mean the regulation of the temperature of the circulating fluid on the cold side—that is, as it passes from the boiler, which is its minimum. This adjunct is indispensable in some of the more complex forms of the process, with several boilers in circuit 60 65 working at different temperatures, and even in the simplest case with only one boiler in circuit it is always desirable. The best method

of effecting this regulation is by a thermostat, and the best method of applying the thermostat is to regulate with it the speed of circulation, so that if the circulating fluid is leaving the boilers too hot its speed may be checked and if too cold its speed may be increased. The best method of doing this latter is to have a circulating-pump throwing some excess over 70 75 the maximum demand for circulation and connected with this pump a thermostatically-controlled by-pass which permits a varying percentage of the liquid pumped to circulate round and round through the by-pass and 80 pump without making the circuit through the heater and boiler or boilers. If the minimum temperature be not regulated, we shall not have a constant mean temperature within the boiler, even though we have a constant 85 maximum, and we shall often have the circulating fluid returning to the heater so hot as to waste much heat.

It is possible to regulate the minimum temperature without controlling the speed of circulation. For instance, if there be a perfectly-uniform withdrawal of steam and supply of working substance circulating fluid which enters the boilers at a constant maximum will leave them at a constant minimum. 90 95 We may also arrange to vary the proportion of the boiler-surface which is active by varying the area which is immersed in working substance; but this variation of extent of active surface is preferably a feature of the 100 control of the quantity or pressure of steam generation, as explained later, when it is used at all.

The thermostat by which the speed or volume per minute of the circulation is regulated I term the "cold thermostat." It should be sensitive and quick-acting, checking the circulation almost completely as soon as the circulation begins to run too hot, as it will as soon as withdrawal of steam is checked, and 105 110 opening wide as soon as it begins to run a few degrees too cold. It should be adjustable, so that it may be set for any desired temperature.

When the withdrawal of steam from the boiler suddenly stops, even though the cold 115 thermostat may promptly stop the circulation, the boiler-passages will be full of hot circulating fluid, which is hotter than the contained working substance by the amount of the transmission interval, which may in cases 120 125 be as much as 100° centigrade, or even more. Hence, as soon as withdrawal of heat stops, the boiler temperatures and pressures will equalize with the circulating fluid, and there will be a quick rise of pressure. The precaution which is generally preferable against this quick and certain increase of pressure is not to use such high circulating temperatures and large transmission intervals as to produce a dangerous pressure even when steam withdrawal stops—as, for instance, one exceeding thirty to forty atmospheres, which well-designed boilers of the type hereinbelow described may easily stand. On this account,

chiefly, it is not expedient to try to force a boiler up to its ultimate capacity, which seems to vary directly with the thermal head; but in cases it may seem necessary or expedient 5 to do this or excessive temperature may result from some accident without intention. Whenever this is deemed possible, it makes regulatory adjunct E, described below, desirable.

¹⁰ *Adjunct E.—Regulation of Quantity of Working Substance in Boiler.*

Whenever a condenser is included as part of the engine process this regulatory adjunct ¹⁵ may conveniently be omitted, because the working substance then works in closed cycle and a pump of whatever type keeps the condenser nearly or quite empty by pumping all working substance as fast as liquefied back ²⁰ into the boiler, thus maintaining it therein at what will be, except for possible carelessness, a sufficiently-constant level.

For the practical reason that pure feed-waters are scarce and impure ones would ²⁵ rapidly coat the thin and highly-active surfaces which I prefer for my boilers I contemplate nearly always using a condenser, whether or not any considerable vacuum is aimed at, and whether or not a supply of condensing-water is available. To this end I have devised a type of evaporative condenser, hereinafter described, which requires no ³⁰ more water than would otherwise be required for feed-water, which is extremely compact, and which will readily give a considerable ³⁵ degree of vacuum, if desired, and at all times enable the feed-water to be used over and over, and thus to maintain a tolerably-constant water-level in the boiler. When no ⁴⁰ condenser is thus connected with the boiler, however, it is highly important that the water-level in the boiler should be regulated to the extent of insuring that it shall not rise above a certain level, because, should it do so, the ⁴⁵ boiler is of such small interior capacity, and so nearly full of liquid at best, that the irresistible force of liquid expansion may be called into action and the boiler ruptured. It may be so simply effected, moreover, that it ⁵⁰ may be better in all cases of importance to regulate the water-level directly, whether or not a condenser be used. Any one of a variety of well-known mechanical devices may ⁵⁵ be used to effect this regulation. The proper one to select depends, primarily, on how the feed-pump is driven, whether directly from the engine, by a separate engine, by electricity, or by the direct action of steam. I prefer the latter method, and the regulating ⁶⁰ device which I deem best consists of nothing more in substance than a little ball-valve float, which when the water-level rises too high rises and closes the aperture through which steam escapes to work the pump, as fully ⁶⁵ described hereinafter.

Adjunct F.—Regulation of the Degree of Pressure that can Exist in the Boiler.

This adjunct may best be secured by a mere water safety-valve, through which, ⁷⁰ when the steam pressure reaches a certain excess above the desired working pressures, just before it reaches the pressure at which the steam safety-valve is set to open, all liquid is blown out of the boiler through the ⁷⁵ feed-pipe or other suitable connection. This liquid may either be discharged to waste or blown back into the working-substance supply or into the condenser. The last is preferable, if there be a condenser. The pump, ⁸⁰ if operated by direct action of steam, will then immediately begin to return the water to the boiler, but will not be able to do so in any quantity until the pressure falls below that at which the liquid blow-off opens, either ⁸⁵ because of cooling or of starting the engine. When the pressure thus falls, however, the boiler will then immediately begin to fill, and if provided with adequate pumping-power will fill up to the level at which the immersed ⁹⁰ surface will just suffice to generate steam at the rate at which it is being drawn off for the time being or to the level fixed by adjunct E.

The adjuncts above described relate particularly to the generation of the vapor-pressure. There are also certain useful results which may be secured by special applications of the circulating fluid, which make the complete process more economical. Among these ⁹⁵ the two following are the most important, and in connection with features of the process above described form parts of the invention.

The circulating fluid is particularly suitable for jacketing the engine-cylinders as ¹⁰⁵ now usual with steam, and it is preferably thus applied when my improved process is used in connection with expansion-engines. Its chief advantages for this purpose are that it is or may be at a higher temperature than ¹¹⁰ the steam, while not too high, and no provisions are required for taking care of the water of condensation, nor for making the steam-jacket steam-tight, nor for making it capable of resisting pressure, except that of the circulating fluid when the latter is circulated under pressure.

The circulating fluid, after having subserved its function of supplying heat to the working substance, may be used to condense ¹²⁰ the vapor of the working substance, and thus be partially heated before its return to the heater. With a single boiler there is no advantage in thus running the circulating fluid through a condenser, unless the circulating ¹²⁵ fluid be cooled between the boiler and condenser, since it is not cooled enough in one boiler to absorb any otherwise waste heat on its way back to the heater; but if two boilers in circuit be used instead of one, the second ¹³⁰

one of which should or may use a more volatile working substance than the first, the circulating fluid will be cooled enough by the second boiler to be able to absorb some waste heat from the engine of the first boiler. In that case the circulating fluid would pass through a second boiler after the first, then through the cold thermostat, and then through a condenser interpolated in the cold circulation-pipe V', as outlined in Fig. 8. Of course the same advantage exists in using the circulating fluid for condensing if the fluid be cooled after leaving the first boiler by its use for any other purpose than for a second boiler.

Some of the betterments of the engine process proper or modes of using steam, which are made possible by the superior methods of steam generation so far described, are illustrated in Figs. 2 to 7, and may be thus described.

In the ordinary engine process the great thermal interval between the temperature of combustion and the boiling-point of water under pressure is unutilized. The heat supply is lowered in temperature through the whole of this interval without dynamic gain. Having our circulating fluid, however, heated to a considerably-higher point than we require for our engine a , Fig. 2, and yet at a regulated and approximately constant temperature, and having the power to work with low thermal heads from the construction of the boiler, it is obvious that we have in this difference of temperature T T' , Fig. 2, a working interval in which we may, if we please, work one or more additional heat-engines, using water or any other liquid or gas as a working substance. In Fig. 3 is illustrated to a rude vertical scale of temperatures one way in which we may do this, and with much advantage, since four engines are in effect run with no greater rejection of heat than otherwise results from the use of two. In this construction the engines a and a' are alone worked under the usual conditions for high-pressure engines, receiving at each stroke a new supply of steam and exhausting it wastefully into the atmosphere. The engine a'' receives its heat directly from the circulating fluid in the same manner as engine a , but at a considerably-higher temperature and pressure and compounds or transmits its waste heat to a' . The fourth engine a''' receives its heat from the circulating fluid indeed, but in such manner as not to finally lower its temperature, the circulating fluid being returned into the heater one or more times after supplying heat to the boiler of a''' , so that its original temperature may be restored. There is thus left a sufficient thermal interval for the engine a''' to work in and yet void the heat in its exhaust at such a high temperature that it may be used to do about half the work of heating up the circulating fluid through an appropriate condenser, and hence the engine a''' may use any working substance in closed cycle, preferably one of higher boiling-point than water, so

that the working pressures due to its temperatures may not be excessive. These four engines may be arranged mechanically in any way desired, the sole necessary condition being that the circulating-passages of their boilers shall be connected in such manner that the circulating fluid shall follow the following path, starting from the heater: heater, 70 boiler of a''' , back to heater to be reheated to original temperature, boiler of a'' , where circulating fluid loses heat, boiler of a , where it loses more heat, condenser of a''' , where the rejected heat of engine a''' is reabsorbed 80 into the circulating fluid; heater, to be reheated and repeat circuit.

In Fig. 4 is illustrated a still simpler way in which two engines may be run with a saving of about half the heat supply of one engine. 85 The circulating fluid is assumed to have only half the volume or mass V per stroke in Fig. 4 that it has in Fig. 3, so that the same quantity of heat, which is that necessary to run the engine a , cools the circulating fluid 90 through twice as great an altitude of temperature. The engine a' , by circulating-passages not indicated on the diagram, is supplied with heat from H at the temperature T' without permitting the circulating fluid to be 95 finally lowered in temperature thereby, which latter is effected by returning the circulating fluid to the heater to be reheated to temperature T' after supplying heat for the engine a' . After being thus reheated, however, the 100 circulating fluid supplies heat to the engine a and is thereby lowered in temperature to T' , which is cold enough to permit the returning circulating fluid to absorb half or more of the 105 exhaust of waste heat of the engine a by passing through its condenser on its way back to the heater, thus relieving the heater of this proportion of the work which would otherwise fall upon it, with corresponding economy. The two engines may have any desired relation to each other mechanically, as before. The sole requirement is that the circulating-passages shall carry the circulating fluid in the cycle described and shown.

In Fig. 5, which is drawn immediately below the single-engine diagram, Fig. 2, to facilitate comparison, is illustrated how, by substituting three engines for the single engine a , each working from a little lower maximum temperature than the preceding one, additional power may be attained under the identical thermal conditions of Fig. 2, with the sole exception that we avail ourselves better of the thermal range open for work by actually working through a greater portion of it, as indicated by the comparative hatched areas of Figs. 2 and 5. The hatched areas of Fig. 5 imply working the steam of the first two of its three engines through compound cylinders, whereas the hatched area of Fig. 2 implies only a single cylinder; but otherwise they are the same, the quantity of heat received and voided and the manner of doing so being essentially identical, except that the

thermal heads are smaller in Fig. 5, and hence the boiler heating-surfaces must be correspondingly greater. With the types of boilers hereinbefore and hereinafter described 5 heating-surface is gained so cheaply and compactly that this is no great matter.

Figs. 6 and 7 show how the amount of work shown in Figs. 3 and 4 may be increased in precisely the same way as that shown in Fig. 10 2 was increased to that shown in Fig. 5 by tripling the number of engines and boilers worked within an identical thermal range, so as to avail ourselves more completely of our whole thermal interval for work.

15 In Fig. 6 the cycle of the circulating fluid, the sole rigid condition for any desired mechanical arrangement, is as follows: heater, boiler of first engine a''' and back to heater, boiler of second engine a''' and back to heater, 20 boiler of third engine a''' and back to heater, boiler of first engine a'' , boiler of second engine a'' , boiler of third engine a'' , boiler of first engine a , boiler of second engine a , boiler of third engine a , condenser of third engine 25 a''' , condenser of second engine a''' , condenser of third engine a''' , and back to heater to repeat the circuit.

Figs. 2 to 7 are designed to be merely illustrative and not at all to give either the only 30 methods or those of highest efficiency employing my improved engine process, some of which latter are made the subject of separate applications. On the contrary, the details of the primary process covered by this application 35 may from its nature be varied almost indefinitely.

It will be understood by those skilled in the art to which the invention relates that the process above described may be carried out by 40 apparatus widely different in construction, arrangement, and mechanical detail, and the invention, considered broadly, is not to be limited to any particular form of the apparatus employed or of the devices forming 45 parts thereof. In Figs. 9 to 18, however, I have shown, largely in diagram, a simple apparatus for carrying out the complete process, this apparatus and the special devices shown being well suited for the purpose, and the 50 general combinations of this apparatus and certain specific features of the same form part of the invention covered by this application.

The most important features of the apparatus relate to the boilers or pressure-generators 55 and the condensers or coolers, with their connections to the heater and the attachments for performing the functions pointed out above, as desirable, it being understood that this apparatus may be used with any particular type of expansion heat-engine doing work through the expansion and consequent cooling of a confined working substance.

Externally the heater II may be of any suitable 60 construction, being preferably a plain iron box lined internally or externally, or both, with non-conducting material, as usual in such constructions. The furnace, if for anthracite,

is preferably of the ordinary base-burner variety, as shown, provided with the fire-box A, fed from the central magazine D and provided with the rocking grate b. The cold circulating fluid enters at the base of the heater, passes upward through the coil of pipes V, about the vertical partition C to the top of the heater, thence downward outside the heater 70 in the pipe V into the annular fire-pot chamber F, whence it passes upward through the inner vertical pipes V to the top annular or manifold G, and thence through the circulation-pipe V outside the heater, onward to the 75 expansion-tank and boiler.

The air supply is regulated externally by any suitable damper to about the volume required for combustion; but there should be some excess of this supply, and to effect a 80 more accurate automatic regulation it is preferably subdivided, the air which supports combustion entering directly under the grate through passage I, and a portion, which serves to insure complete combustion and to dilute 85 the gases of combustion and check the fire when desired, entering above the fire-pot through the passage I', these passages being controlled, respectively, by flap-dampers d d'. From the fire-pot the mixed air and products 90 of combustion pass through the perforated shield e, and then are deflected outward by the cone K between the pipes V, connecting the annulars or manifolds F G, thence passing upward over the partition C, forming the inner furnace-chamber, and downward between 95 and about the coil of pipes V, entering the flue L at the base of the furnace, whence they escape by the pipe L. In case the fires are giving out too much heat, however, as is assumed in Fig. 9, a thermostatically-controlled 100 damper f closes L and opens a direct connection M for the escape of the gases.

The maximum temperature of the circulating fluid, as above stated, is preferably regulated by a thermostat, which, together with the attachments by which this regulation is secured, may be of any suitable form. I have shown, however, a simple thermostat, which will be found efficient, and this thermostat is 110 preferably placed between the heater II and expansion-tank T, and in the form shown consists of a stout wooden rod T^h, placed parallel with and adjacent to the circulating-pipe V, this portion of the pipe being formed, preferably, of a thick well-lagged brass or copper tube. As the wooden rod does not change in length with temperature, while the brass or copper tube expands largely and will be sensibly of the same temperature as the circulation, the relative length of the tube and rod gives a positive, simple, and powerful thermostat. While the circulating-pipe is shown 115 as part of the thermostat, it will be understood that a tube may be added to form the 120 thermostat, if desired, instead of using the circulating-pipe. For the purpose of transmitting the movements of the thermostat a lever N is pivoted upon the end of the rod T^h, 125

with its short arm connected to the pipe V at the end of the portion used for the thermostat, its long arm being connected by a chain 10 to one end of a weighted lever g, connected by another chain 10 to a bell-crank lever h, from one end of which a connecting rod or rods 11 run to the dampers d d', and from the other end of which a connecting-rod 12 runs to the damper f. By these connections the damper 5 d is closed and d' opened when the temperature reaches the point for which these parts are set and the reverse as the temperature falls, and the damper f is actuated to open the passage M for the products of combustion. 10 when the temperature rises to a certain point and to close the passage M more or less as the temperature falls, the relative times of opening and closing of the dampers d d' f being adjusted as desired, as by lost-motion connections 15 in case a single connection from the lever N is used, the rod 11 being shown as passing through a weighted arm on damper d' and carrying a stop by which this arm is raised and the valve closed against the weight, which 20 operates to open the damper as the temperature rises. The particular form of the connections may be varied to suit mechanical convenience. This thermostat also controls the grate-shaker by the connections shown in 25 Fig. 17, the grate b being actuated by a crank-arm 13, connected by a link 14 to a crank-arm 15 on a crown-wheel i, which is mounted in a frame k, pivoted to a fixed part of the construction and connected either to the rod 11, 30 or as shown for the sake of clearness, connected by an independent rod 16 to the weighted lever g, so that the frame k will be raised by the weighted lever as the temperature falls, and will be lowered by its own 35 weight when released by the lever as the temperature rises. The crown-wheel i, when in its upper position, engages with a worm l, driven continuously by suitable connection with the engine or an independent motor. 40 To prevent excessive wear on the wheel i, which would be caused by the wheel being brought into contact with the worm l gradually, some device is preferably provided by which the throwing of the wheel i into and out 45 of contact with the worm l shall be instantaneous. In the construction shown, a bent spring 9 is used, engaging the end of the frame k, the spring resisting and preventing the movement of the frame k in either direction 50 until its resistance is overcome, when the frame moves quickly. An adjusting-screw 50 gives means for regulating the resistance of the spring-catch 9.

A safety-valve t, controlled by the temperature, is preferably used on the expansion-tank T, and this safety valve is shown as actuated from the thermostat-lever N by the following connections: The valve t is normally closed by a weighted arm 47, through which passes 60 a rod 48, connected to the lever N, the rod 48 being provided with a stop which engages the weighted arm 47 to raise and open the valve

t at the proper time, the valve being closed by the weight when the arm is released as the temperature falls. This same rod 48 may operate also the three way-valve x, controlling the change of circulation from the boiler to the evaporative tank Z, and is thus shown, the valve-stem 49 being weighted and the rod 48 passing through it and being provided with 70 a stop which engages and actuates the arm at the proper time to open the valve and change the circulation from the pipe V to the pipe V², the valve being shifted so as to close pipe V² and open pipe V to the boiler again by the 75 weight on stem 49 as the temperature falls. At the lower end of the pipe V² a valve y is placed, which need only be a check-valve of any suitable form permitting liquid to pass freely downward, but not upward. It will 80 be understood that all these various valves and dampers for regulating the maximum temperature and connections therewith to the thermostat may be of any suitable form, and that the constructions shown are selected only 85 as a convenient way of illustrating means for securing the desired results.

In practice it will be found preferable in different cases to use single or independent connections from the thermostat for the various devices, depending upon the mechanical construction and arrangement adopted for the heater and other parts of the apparatus. The construction shown, therefore, is simply 90 illustrative and largely diagrammatic. 100

It will be seen from the above description that this maximum temperature thermostat, as shown, effects the following ends, the order given being that in which the motions occur, starting as the heat increases, the position of 105 the parts in the drawings being that at which the temperature has risen to a point where the regulating devices connected with the heater are brought into action, but before the shifting of the circulation or opening of the 110 relief safety - valve: first, regulation of the maximum temperature of the circulating fluid through the fuel-supply by disconnecting the 115 grate-shaker; second, regulation of the maximum temperature of the circulating fluid through the air-supply by first closing the 120 damper d, controlling the air-inlet I below grate, and then opening damper d', controlling the air-inlet I' above grate; third, regulation of the maximum temperature of the circulating fluid by opening damper f, controlling passage M, so as to permit the hot gases 125 to pass directly upward to the flue L, instead of taking the more circuitous downward course over the heating-surfaces formed by the coils of pipes V; fourth, regulation of the maximum temperature of the circulating fluid by diverting the circulating fluid into an evaporative - tank; fifth, regulation of the maximum temperature of the circulating fluid 130 by opening safety-valve positively.

To provide for the remote contingency that the heat shall become excessive after some or all of these regulative features have come into

action, or for some possible disarrangement of the thermostat on which they all depend, an ordinary loaded safety-valve should also be added, forming a further safeguard. These 5 several safeguards may come into action at intervals of 5° to 10° centigrade, or other suitable intervals, as may prove to be best in the particular case. Each should have its independent adjustments, which once set will 10 rarely need to be disturbed.

The circulating-pipe V passes through the expansion-tank T on its way from the boiler to the heater, and this tank is supplied from the supply-tank S, devices being provided by 15 which the volume of the circulating fluid is kept sensibly constant, regardless of temperature. The preferable construction by which this result is secured is shown in Fig. 10, and is as follows: A good-sized float 1 in the expansion-tank T is carried by a rod 2, the float having a certain amount of free motion in either direction without action on the valves, but at the limit of the free motion in either direction operating one of two small valves 3 20 at top and bottom of the tank, which valves may be of any suitable form and arranged in any suitable manner so as to be actuated by the rod 2 in the manner desired. The valve 3 controls a pipe 4, connecting the top of the expansion-tank T with the top of the supply-tank S, and the valve 5 controls a pipe 6, connecting the bottom of the supply-tank S with the bottom of the expansion-tank T. If the float rises too high it opens the lower valve 5 25 and permits fluid to be blown out by the interior pressure through the pipe 6 into the supply-tank S. If the float falls too low it opens the upper valve 3, which permits pressure to equalize in the steam-space of tanks S and T, 30 when liquid will flow by gravity into tank T from the tank S through valve 5 or another check-valve 7, connecting pipe 6 with tank T, and opening inward to the tank, or through both of these valves, until the valve 3 is closed 35 again. Such closure of the valve 3 results in speedy lowering of the pressure in supply-tank S by condensation and consequent cessation of flow.

An air-valve 8 may be added in the top of the 40 tank S to prevent the formation of a vacuum in this tank, and thus to decrease the quantity of steam which must pass over to equalize pressure. If, however, the nature of the circulating fluid is such as to generate little pressure, 45 a vacuum in the supply-tank may be found desirable. If it be desired to guard against the contingency that the valve 5 may be stuck or otherwise inoperative, the valve 7, in addition to its function of admitting fluid from pipe 6 to the tank T, may be so constructed as to let 50 liquid escape when the pressure in tank T rises above a fixed maximum. This is not absolutely essential, however, as the tank T should, in any case, be provided with a common safety-valve, as above stated.

The expansion-tank T and supply-tank S, as shown and described, placed at the top of the

system, secure the regulation of the volume of circulating fluid whether the circulation be natural under the conditions produced by the 70 heater or produced or aided mechanically, as by a circulating-pump.

From the expansion-tank T the circulating fluid passes through pipe V to the boiler B. The boiler may have any form whatever and 75 still be effective, as already explained, and my improved boiler process may be carried out with boilers of widely-different form, provided only that the circulating fluid enters at or near the top and passes downward through heating- 80 passages in the interior to or near the bottom, while the working substance enters at or near the bottom and passes upward to a steam-escape at or near the top. It is preferable, however, as above stated, to use a large number of 85 small passages for the circulating fluid, and for such a boiler employing tubes to form these passages the particular form shown offers many advantages. This boiler, as shown in detail in Figs. 11, 12, and 13, consists internally of successive layers of small horizontal tubes n, uniformly spaced and preferably set closely together in layers crossing each other, and almost touching, as shown about full size in Fig. 13. This gives the boiler proper a 90 square cross-section, as shown in Fig. 12, the four sides of the square being tube-sheets, occupied by tubes from top to bottom, the alternate layers or groups of two or more layers, of tubes extending at right angles to each other and opening at alternate sides of the boiler. By this peculiar construction several important ends are attained: First, the tubes are more closely spaced than is otherwise possible, since holes for only each 95 alternate layer occur in each tube-sheet, so that the holes for the tubes do not interfere with each other, and uniformity of spacing may be readily assured; second, each tube stays a nearly constant and small area of 100 tube-sheet, and for each such area there is a tube to stay it, so that the tube-sheets may be thin and of constant thickness, regardless of the size of the boiler, providing that the 105 size and spacing of the tubes remain constant; third, the internal evaporative conditions are better than with parallel tubes; fourth, the boiler may be constructed by 110 pan-brazing of the tubes, and the corners also may be brazed at one dip of each face. The 115 vertical corners are merely rounded to overlap, as shown in Fig. 12, and brazed together at the same time as the tubes, and the top and bottom of the boiler are brazed onto the sides at the same time, being shaped as described 120 hereinafter. The square boiler thus formed is slipped inside of a cylindrical casing p, which may be of any thin sheet metal if the 125 circulating fluid be not circulated under pressure. If it be so circulated, the casing 130 must be of thickness adequate to resist the pressure. In slipping in the boilers some form of spring-contact is preferably effected at two opposite corners, and preferably also

at the remaining corners, which makes these corners practically water-tight against any trifling pressure. It is not necessary that they should be absolutely water-tight; also, before the boiler is slipped into the spring p , certain thin segmental plates 17 are added either to the outside of the boiler or to the inside of the casing, thus forming partitions dividing the space about the boiler within the casing into chambers, these partitions having preferably spring or feather edges, which makes them practically water-tight against any trifling pressure. It is not necessary that they should be absolutely water-tight. The upper partition 19 is the same as the others, except that with the construction shown it is not flat but curved, so as to cover the ends of the tubes which fill the upper portion of the boiler under the concave cap. The caps 18 on the outer casing are then put on, these caps being preferably shaped so as to be sections of a sphere having a radius equal to the diameter of the casing, so that they will be of equal strength therewith if of the same thickness. The two boiler ends are preferably of the same form and radius as the caps, but need a thickness proportional to their size regardless of the thickness of the tube-sheets, since they are not stayed by tubes. They may also need to be tied together by more metal than is contained in the tube-sheets, which may be effected by tubular or other stays at the corners, which may also serve to effect the spring-contact at these corners above referred to. Each of the caps is also provided with a central opening or pipe through which the circulating-pipes V and V' connect at top and bottom with the interior of the casing p , the circulating fluid entering at the top of the casing and leaving at the bottom. Through this opening also enters the boiler-feed pipe 20 at the bottom of the casing, and from the top issues from the boiler the steam-pipe O. With the boiler thus constructed the dotted lines in Fig. 11 indicate the path of one portion of the circulating fluid in passing through the boiler. This fluid enters at the top and fills what is in effect a top storage-chamber above the boiler within the casing, from which there are only two openings—viz., two of the segmental areas between the boiler and the casing above the top partitions 19—each of which areas give access to one or more of the upper layers of tubes. Dividing between these in about equal volume the circulating fluid in two distinct masses follows the zig-zag path indicated by the arrows and a path at right angles thereto until it reaches the bottom chamber, wherein the two masses reunite and pass out through the cold circulating-pipe V' at the bottom of the casing, and thence pass together to the next boiler, if two or more boilers are employed, as shown in Fig. 8, or to one or more condensers or return directly to the heater, as in the con-

struction shown in Fig. 9. The number of possible partitions 17 is limited only by the number of layers of tubes n . The more partitions are used the faster must be the current to pass a given mass of circulating fluid per minute, and hence, as experiment indicates, the higher the transmitting efficiency of the surfaces in a ratio approximating to the square root of the velocity. It is expedient, therefore, to have as many of these partitions as mechanical convenience permits. There is a surprising absence of any tendency to foam in boilers constructed as described, despite the close spacing of the tubes, which would seem to insure it. The differential temperatures of the circulating fluid corresponding to the different layers of the working substance seem to prevent this. The boiler is also so small that any attempt to increase its steam-generating capacity seems almost superfluous. Nevertheless foaming may at times result with some working substances, and this may be prevented and the effective heating-surface per cubic foot substantially increased at the same time by interposing between each two layers of tubes and in contact therewith a sheet of fine wire-gauze, as shown in Fig. 13 at 100, having from thirty to sixty meshes per inch, (twelve to twenty-four per centimeter.) This gauze does not diminish the effective opening for the passage of the working substance upward. On the contrary the proportion of open space to total area is about the same in wire-gauze of all commercial sizes as exists between the tubes at the middle thereof; but the addition of the gauze does insure that every particle of steam and liquid shall be repeatedly in immediate contact with hot surfaces as it rises, because the gauze sheets are in immediate contact with hot tubes both above and below them, and both by radiation and conduction will be supplied in all parts with heat, which they will surrender to the working substance as it passes them as effectively as do the tubes themselves. The one serious objection which applies to the use of such gauze applies also to the boiler itself without the gauze. The surfaces are so small and so closely spaced, and the quantity of liquid evaporated per cubic foot and per square foot of surface is so very great that the slightest impurities in the working substance will tend to accumulate rapidly, coating the surfaces and clogging the interspaces, if each mass of working substance is used only once. Against this there is the compensating advantage that as the boiler is exposed to low temperatures only these deposits are not likely to cake on, as in fire-boilers; but for a considerable time, at least, will remain in a soft and pulpy state, so that they may be blown out by a reverse current through a blow-off valve, in the usual way. Also, the cubic contents of the boiler are so small that no great loss of time or heat ensues from blow-

ing off very frequently. In this manner any tolerably-pure water-supply may be used in open cycle without condensers. Nevertheless, the only entirely effective precaution 5 against these deposits is to use condensers always, whether a vacuum is desired or not, for the mere sake of using the same working substance over and over.

The branch pipes 21 22, connecting, respectively, with the feed-pipe 20 and steam-pipe O, form the means of attachment for several boiler adjuncts, which are preferably employed and connected substantially as shown in Fig. 9 and in detail in Fig. 14. These adjuncts include an ordinary safety-valve, a steam-gage 23, and an ordinary water-gage 24. The safety-valve is not shown, as it may be of any common construction. It practically never opens, and is preferably a mere 20 leaf-spring closing an aperture in pipe 22 or steam-pipe O. The steam-gage 23 and water-gage 24 will not be so steady if connected, as shown, to branches of the steam-pipe and feed-pipe as if connected to separate apertures in 25 the boiler itself; but the construction shown is sufficiently convenient to overbalance this disadvantage in most cases.

A charging-can 25 for adding to or subtracting from the constant mass of fluid, which in 30 the construction shown is circulated in closed cycle between the boiler, engine, and condenser, is also shown, this can having a separate water-gage 26. When a condenser is used, this adjunct is not needed, and its use 35 is always rather a convenience than a matter of importance; but it is preferable to employ this can with the connections shown rather than to rely on a pump to pump liquid in or out of the circulating mass of working substance. At the top the charging-can 25 is connected with the steam-pipe by the pipe 22, controlled by the cock 28, and at the bottom it is connected with the feed-pipe 20 through the pipe 21 and a pipe 29, controlled by a 40 cock 30. Liquid is introduced into the charging-can 25 by the funnel m. As it may be noxious or highly volatile, this funnel is preferably provided with an interior female thread into which a nozzle may be screwed to 45 give an air-tight connection, and a similar cock 31 is provided at any suitable point for drawing off liquid from the charging-can. This charging-can must be made strong enough to resist any boiler pressure, but need not be 50 large. To remove liquid from the system into the charging-can the cock 30 is opened, when the interior pressure in the system will blow back as much liquid as desired into the can up to its full capacity, with or without a 55 slight opening of the cock m to release any confined air or gas. To introduce liquid into the system the cock 28 is first opened, letting boiler-pressure into the can, and then opening the cock 30 allows the liquid to flow into the 60 boiler through pipes 29 21 by gravity.

A water blow-off valve 27 acting antecedently to the safety-valve is preferably used,

through which an excessive boiler pressure will blow back all liquid in the boiler into the condenser or elsewhere, and thus secure a 70 regulation of the maximum pressure in the boiler independently of the safety-valve. This water blow-off valve 27 may be of any type which opens at a fixed interior pressure and closes when that pressure ceases and 75 may be introduced at any point where it is in open connection with the bottom of the boiler, either on the boiler or a branch pipe, as shown.

The supply of water to the boiler is regulated in the construction shown, by the control of the steam-supply to the feed-pump, according to the water-level of the boiler. This control may be secured by any suitable means, but a simple and efficient construction of regulative valve is shown. This regulative valve is used in cases in which the feed-pump is an independent mechanism driven by an independent steam-supply, and any suitable pump of this character may be used. The feed-pump may draw the water from an external supply or from a condenser, as shown. When it draws from a condenser, this regulative valve may not be found necessary. As shown, the compound pipe 33 34 constitutes, in effect, 95 an ordinary water-gage automatically controlling the steam-supply to the feed-pump, pipe 33 being in open connection with the water-space through pipe 21, and pipe 34 with the steam-space through pipe 22. From the 100 chamber at the top of pipe 23 a small steam-pipe 35 leads to the feed-pump p', and 36 is a small ball-float in this chamber, this ball-float being arranged to close pipes 34 35 and cut off the steam-supply in its top position and open 105 them to supply steam to the feed-pump when lowered by the fall of the water in the boiler and pipe 33. It is not necessary that this ball-float should have a very tight seat, as any small amount of steam leaking by it will condense instead of operating the pump. In the steam-pipe 35, a pressure-reducing valve of any suitable form should ordinarily be added to stop the pump by the resistance at a certain pressure in the boiler and prevent any 110 more than a desired maximum working 115 boiler-pressure.

The circulating fluid may pass from the boiler B to another boiler or boilers or other devices for utilizing the heat, and then return 120 to the heater directly or through one or more condensers, or, as in the simple construction shown in Fig. 9, return directly from the boiler to the heater. In this construction the circulating fluid passes from the boiler 125 through the pipe V' to a circulating-pump P, which, as shown, consists of a chamber or enlargement on the pipe V', in which runs a screw or other force pump Q, which may be driven in any suitable manner, a belt and 130 pulley r being shown for this purpose. Upon the pipe V', between the boiler and circulating-pump P, is placed the cold or minimum thermostat Th', by which the speed of

23. The improvement in the art of converting heat into work by the agency of vapor pressure, which consists in passing a circulating fluid from a supply or source of heat to a pressure generator thermally dissociated from said supply or source of heat and containing the working substance, regulating the maximum and minimum temperature of the circulating fluid, regulating the volume of the 5 circulating fluid to maintain a substantially constant volume, regulating the volume of the working substance to maintain a substantially constant volume, applying the circulating fluid to heating the hotter and colder parts 10 of the working substance successively by passing it downward through the pressure generator, and discharging the circulating fluid from the pressure generator, substantially as described.
24. The improvement in the art of converting heat into work by the agency of vapor pressure, which consists in passing a circulating fluid at a regulated speed from a supply or source of heat to a pressure generator 15 thermally dissociated from said supply or source of heat and containing the working substance, passing the circulating fluid through passages first in the steam space and then in the water space of said generator and downward from the hotter to the colder parts of the working substance, and discharging the circulating fluid from the pressure generator, substantially as described.

25. The improvement in the art of converting heat into work by the agency of vapor pressure, which consists in passing a circulating fluid from a supply or source of heat to a pressure generator thermally dissociated from the supply or source of heat and containing the working substance, heating the working substance by the surrender of heat thereto by the circulating fluid, applying the vapor pressure and then exhausting the vapor into a condenser and cooling it by the circulating fluid after the latter is discharged from the pressure generator, substantially as described.

26. The improvement in the art of converting heat into work by the agency of vapor pressure, which consists in passing a circulating fluid at a regulated temperature from a supply or source of heat to a pressure generator thermally dissociated from the supply or source of heat and containing the working substance, heating the working substance by the surrender of heat thereto by the circulating fluid, applying the vapor pressure and then exhausting the vapor into a condenser and cooling it by the circulating fluid after the latter is discharged from the pressure generator, substantially as described.

27. The improvement in the art of converting heat into work by the agency of vapor pressure, which consists in passing a circulating fluid from a supply or source of heat to a pressure generator thermally dissociated from the supply or source of heat and con-

taining the working substance, regulating the minimum temperature of the circulating fluid, heating the working substance by the 70 surrender of heat thereto by the circulating fluid, applying the vapor pressure and then exhausting the vapor into a condenser and cooling it by the circulating fluid after the latter is discharged from the pressure generator, substantially as described.

28. The improvement in the art of converting heat into work by the agency of vapor pressure, which consists in passing a circulating fluid at a regulated speed, from a supply 80 or source of heat to a pressure generator thermally dissociated from the supply or source of heat and containing the working substance, heating the working substance by the surrender of heat thereto by the circulating fluid, 85 applying the vapor pressure and then exhausting the vapor into a condenser and cooling it by the circulating fluid after the latter is discharged from the pressure generator, substantially as described.

29. The improvement in the art of converting heat into work by the agency of vapor pressure, which consists in passing a circulating fluid from a supply or source of heat to a pressure generator thermally dissociated from the supply or source of heat and containing the working substance, regulating the maximum and minimum temperature of the circulating fluid, heating the working substance by the surrender of heat thereto by the circulating fluid, applying the vapor pressure and then exhausting the vapor into a condenser and cooling it by the circulating fluid after the latter is discharged from the pressure generator, substantially as described.

30. The improvement in the art of converting heat into work by the agency of vapor pressure which consists in passing a circulating fluid from a supply or source of heat to a pressure generator thermally dissociated from said supply or source of heat and containing the working substance, applying the circulating fluid to heating the hotter and colder parts of the working substance successively by passing it downward through the pressure 115 generator, applying the vapor pressure and then exhausting the vapor into a condenser and cooling it by the circulating fluid after the latter is discharged from the pressure generator, substantially as described.

31. The improvement in the art of converting heat into work by the agency of vapor pressure, which consists in passing a continuously moving circulating fluid at a regulated temperature from a supply or source of heat to a pressure generator thermally dissociated from the supply or source of heat and containing the working substance, heating the working substance by the surrender of heat thereto by the circulating fluid, and returning the circulating fluid to the circulating fluid supply or source of heat, substantially as described.

32. The improvement in the art of convert-

ing heat into work by the agency of vapor pressure, which consists in passing a continuously moving circulating fluid from a supply or source of heat to a pressure generator thermally dissociated from said supply or source of heat and containing the working substance, regulating the maximum temperature of the circulating fluid, heating the working substance by the surrender of heat thereto by the circulating fluid, and returning the circulating fluid to the circulating fluid supply or source of heat, substantially as described.

33. The improvement in the art of converting heat into work by the agency of vapor pressure, which consists in passing a continuously moving circulating fluid from a supply or source of heat to a pressure generator thermally dissociated from said supply or source of heat and containing the working substance, 15 regulating the minimum temperature of the circulating fluid, heating the working substance by the surrender of heat thereto by the circulating fluid, and returning the circulating fluid to the circulating fluid supply or 20 source of heat, substantially as described.

34. The improvement in the art of converting heat into work by the agency of vapor pressure, which consists in passing a continuously moving circulating fluid from a supply or source of heat to a pressure generator thermally dissociated from said supply or source of heat and containing the working substance, regulating the maximum and minimum temperature of the circulating fluid, heating the working substance by the surrender of heat thereto by the circulating fluid, and returning the circulating fluid to the circulating fluid supply or source of heat, substantially as described.

40 35. The improvement in the art of converting heat into work by the agency of vapor pressure, which consists in passing a continuously moving circulating fluid at a regulated speed from a supply or source of heat to a
45 pressure generator thermally dissociated from the supply or source of heat and containing the working substance, regulating the maximum temperature of the circulating fluid, heating the working substance by the surrender of heat thereto by the circulating fluid, and returning the circulating fluid to the circulating fluid supply or source of heat, substantially as described.

36. The improvement in the art of converting heat into work by the agency of vapor pressure, which consists in passing a continuously moving circulating fluid from a supply or source of heat to a pressure generator thermally dissociated from said supply or source of heat and containing the working substance, regulating the volume of the circulating fluid so as to maintain a substantially constant volume, heating the working substance by the surrender of heat thereto by the circulating fluid, and returning the circulating fluid

to the circulating fluid supply or source of heat, substantially as described.

37. The improvement in the art of converting heat into work by the agency of vapor pressure, which consists in passing a continuously moving circulating fluid at a regulated temperature from a supply or source of heat to a pressure generator thermally dissociated from said supply or source of heat and containing the working substance, regulating the volume of circulating fluid so as to maintain a substantially constant volume, heating the working substance by the surrender of heat thereto by the circulating fluid, and returning the circulating fluid to the circulating fluid supply or source of heat, substantially as described. 70 75 80

38. The improvement in the art of converting heat into work by the agency of vapor pressure, which consists in passing a continuously moving circulating fluid at a regulated speed from a supply or source of heat to a pressure generator thermally dissociated from said supply or source of heat and containing the working substance, regulating the maximum temperature of the circulating fluid, regulating the volume of the circulating fluid so as to maintain a substantially constant volume, heating the working substance by the surrender of heat thereto by the circulating fluid, and returning the circulating fluid to the circulating fluid supply or source of heat, substantially as described. 85 90 95

39. The improvement in the art of converting heat into work by the agency of vapor pressure, which consists in passing a continuously moving circulating fluid at a regulated temperature from a supply or source of heat to a pressure generator thermally dissociated from said supply or source of heat and containing the working substance, regulating the volume of the circulating fluid so as to maintain a substantially constant volume, regulating the quantity of working substance in the pressure generator to maintain a substantially constant volume, heating the working substance by the surrender of heat thereto by the circulating fluid, and returning the circulating fluid to the circulating fluid supply or source of heat, substantially as described. 100 105 110 115

scribed. 40. The improvement in the art of converting heat into work by the agency of vapor pressure, which consists in passing a continuously moving circulating fluid at a regulated speed from a supply or source of heat to a pressure generator thermally dissociated from said supply or source of heat and containing the working substance, regulating the maximum temperature of the circulating fluid, 120 regulating the volume of the circulating fluid so as to maintain a substantially constant volume, regulating the quantity of working substance in the pressure generator to maintain a substantially constant volume, heating the 125 130

ing fluid and discharging the circulating fluid from the pressure generator, substantially as described.

5. The improvement in the art of converting heat into work by the agency of vapor pressure, which consists in passing a circulating fluid at a regulated speed from a supply or source of heat to a pressure generator thermally dissociated from the supply or source 10 of heat and containing the working substance, heating the working substance by the surrender of heat thereto by the circulating fluid, and discharging the circulating fluid from the pressure generator, substantially as described.

15 6. The improvement in the art of converting heat into work by the agency of vapor pressure, which consists in passing a circulating fluid at a regulated speed from a supply 20 or source of heat to a pressure generator thermally dissociated from said supply or source of heat and containing the working substance, regulating the maximum temperature of the 25 circulating fluid, heating the working substance by the surrender of heat thereto by the circulating fluid, and discharging the circulating fluid from the pressure generator, substantially as described.

30 7. The improvement in the art of converting heat into work by the agency of vapor pressure, which consists in passing a circulating fluid from a supply or source of heat to a pressure generator thermally dissociated from said supply or source of heat and containing the working substance, regulating the 35 volume of the circulating fluid so as to maintain a substantially constant volume, heating the working substance by the surrender of heat thereto by the circulating fluid, and discharging the circulating fluid from the pressure generator, substantially as described.

40 8. The improvement in the art of converting heat into work by the agency of vapor pressure, which consists in passing a circulating fluid at a regulated temperature from a supply or source of heat to a pressure generator thermally dissociated from said supply or source of heat and containing the working substance, regulating the volume of circulating fluid so as to maintain a substantially 45 constant volume, heating the working substance by the surrender of heat thereto by the circulating fluid, and discharging the circulating fluid from the pressure generator, substantially as described.

50 9. The improvement in the art of converting heat into work by the agency of vapor pressure, which consists in passing a circulating fluid from a supply or source of heat to a pressure generator thermally dissociated from said supply or source of heat and containing the working substance, regulating the minimum 55 temperature of the circulating fluid, regulating the volume of the circulating fluid so as to maintain a substantially constant volume, heating the working substance by the surrender of heat thereto by the circulating fluid, and discharging the circulating fluid from the pressure generator, substantially as described.

ing fluid, and discharging the circulating fluid from the pressure generator, substantially as described.

70 10. The improvement in the art of converting heat into work by the agency of vapor pressure, which consists in passing a circulating fluid at a regulated speed from a supply or source of heat to a pressure generator 75 thermally dissociated from said supply or source of heat and containing the working substance, regulating the maximum temperature of the circulating fluid, regulating the volume of the circulating fluid so as to maintain a substantially constant volume, heating the working substance by the surrender of heat thereto by the circulating fluid, and discharging the circulating fluid from the pressure generator, substantially as described.

80 11. The improvement in the art of converting heat into work by the agency of vapor pressure, which consists in passing a circulating fluid from a supply or source of heat to a pressure generator thermally dissociated 90 from said supply or source of heat, regulating the quantity of working substance in the pressure generator to maintain a substantially constant volume, heating the working substance by the surrender of heat thereto by 95 the circulating fluid, and discharging the circulating fluid from the pressure generator, substantially as described.

100 12. The improvement in the art of converting heat into work by the agency of vapor pressure, which consists in passing a circulating fluid from a supply or source of heat to a pressure generator thermally dissociated from said supply or source of heat and containing the working substance, regulating the 105 quantity of working substance in the pressure generator to maintain a substantially constant volume, regulating the maximum pressure in the pressure generator, heating the working substance by the surrender of heat 110 thereto by the circulating fluid, and discharging the circulating fluid from the pressure generator, substantially as described.

115 13. The improvement in the art of converting heat into work by the agency of vapor pressure, which consists in passing a circulating fluid from a supply or source of heat to a pressure generator thermally dissociated from said supply or source of heat and containing the working substance, regulating the 120 volume of the circulating fluid so as to maintain a substantially constant volume, regulating the quantity of working substance in the pressure generator to maintain a substantially constant volume, heating the working substance by the surrender of heat 125 thereto by the circulating fluid, and discharging the circulating fluid from the pressure generator, substantially as described.

130 14. The improvement in the art of converting heat into work by the agency of vapor pressure, which consists in passing a circulating fluid at a regulated temperature from a supply or source of heat to a pressure genera-

tor thermally dissociated from said supply or source of heat and containing the working substance, regulating the volume of the circulating fluid so as to maintain a substantially constant volume, regulating the quantity of working substance in the pressure generator to maintain a substantially constant volume, heating the working substance by the surrender of heat thereto by the circulating fluid, and discharging the circulating fluid from the pressure generator, substantially as described.

15. The improvement in the art of converting heat into work by the agency of vapor pressure, which consists in passing a circulating fluid from a supply or source of heat to a pressure generator thermally dissociated from said supply or source of heat and containing the working substance, regulating the maximum and minimum temperature of the circulating fluid, regulating the quantity of working substance in the pressure generator to maintain a substantially constant volume, heating the working substance by the surrender of heat thereto by the circulating fluid, and discharging the circulating fluid from the pressure generator, substantially as described.

16. The improvement in the art of converting heat into work by the agency of vapor pressure, which consists in passing a circulating fluid at a regulated speed from a supply or source of heat to a pressure generator thermally dissociated from said supply or source of heat and containing the working substance, regulating the maximum temperature of the circulating fluid, regulating the volume of the circulating fluid so as to maintain a substantially constant volume, regulating the quantity of working substance in the pressure generator to maintain a substantially constant volume, heating the working substance by the surrender of heat thereto by the circulating fluid, and discharging the circulating fluid from the pressure generator, substantially as described.

17. The improvement in the art of converting heat into work by the agency of vapor pressure, which consists in passing a circulating fluid at a regulated speed from a supply or source of heat to a pressure generator thermally dissociated from said supply or source of heat and containing the working substance, applying the circulating fluid to heating the hotter and colder parts of the working substance successively by passing it downward through the pressure generator, and discharging the circulating fluid from the pressure generator, substantially as described.

60 18. The improvement in the art of converting heat into work by the agency of vapor pressure, which consists in passing a circulating fluid at a regulated temperature from a supply or source of heat to a pressure generator thermally dissociated from said supply or source of heat and containing the working substance, applying the circulating

65

fluid to heating the hotter and colder parts of the working substance successively by passing it downward through the pressure generator, and discharging the circulating fluid from the pressure generator, substantially as described.

19. The improvement in the art of converting heat into work by the agency of vapor pressure, which consists in passing a circulating fluid from a supply or source of heat to a pressure generator thermally dissociated from said supply or source of heat and containing the working substance, regulating the minimum temperature of the circulating fluid, applying the circulating fluid to heating the hotter and colder parts of the working substance successively by passing it downward through the pressure generator, and discharging the circulating fluid from the pressure generator, substantially as described. 75 80 85

20. The improvement in the art of converting heat into work by the agency of vapor pressure, which consists in passing a circulating fluid at a regulated speed from a supply or source of heat to a pressure generator thermally dissociated from said supply or source of heat and containing the working substance, regulating the maximum temperature of the circulating fluid, applying the circulating fluid to heating the hotter and colder parts of the working substance successively by passing it downward through the pressure generator, and discharging the circulating fluid from the pressure generator, substantially as described. 90 95 100

21. The improvement in the art of converting heat into work by the agency of vapor pressure, which consists in passing a circulating fluid from a supply or source of heat to a pressure generator thermally dissociated from said supply or source of heat and containing the working substance, regulating the volume of the circulating fluid to maintain a substantially constant volume, applying the circulating fluid to heating the hotter and colder parts of the working substance successively by passing it downward through the pressure generator, and discharging the circulating fluid from the pressure generator, substantially as described. 105 110 115

22. The improvement in the art of converting heat into work by the agency of vapor pressure, which consists in passing a circulating fluid from a supply or source of heat to a pressure generator thermally dissociated from said supply or source of heat and containing the working substance, regulating the maximum and minimum temperature of the circulating fluid, regulating the volume of the circulating fluid to maintain a substantially constant volume, applying the circulating fluid to heating the hotter and colder parts of the working substance successively by passing it downward through the pressure generator, and discharging the circulating fluid from the pressure generator, substantially as described. 120 125 130

working substance by the surrender of heat thereto by the circulating fluid, and returning the circulating fluid to the circulating fluid supply or source of heat, substantially as described.

41. The improvement in the art of converting heat into work by the agency of vapor pressure, which consists in passing a continuously moving circulating fluid at a regulated speed from a supply or source of heat to a pressure generator thermally dissociated from said supply or source of heat and containing the working substance, applying the circulating fluid to heating the hotter and colder parts of the working substance successively by passing it downward through the pressure generator, and returning the circulating fluid to the circulating fluid supply or source of heat, substantially as described.

42. The improvement in the art of converting heat into work by the agency of vapor pressure, which consists in passing a continuously moving circulating fluid at a regulated speed from a supply or source of heat to a pressure generator thermally dissociated from said supply or source of heat and containing the working substance, regulating the maximum temperature of the circulating fluid, applying the circulating fluid to heating the hotter and colder parts of the working substance successively by passing it downward through the pressure generator, and returning the circulating fluid to the circulating fluid supply or source of heat, substantially as described.

43. The improvement in the art of converting heat into work by the agency of vapor pressure, which consists in passing a continuously moving circulating fluid from a supply or source of heat to a pressure generator thermally dissociated from said supply or source of heat and containing the working substance, regulating the volume of the circulating fluid to maintain a substantially constant volume, applying the circulating fluid to heating the hotter and colder parts of the working substance successively by passing it downward through the pressure generator, and returning the circulating fluid to the circulating fluid supply or source of heat, substantially as described.

44. The improvement in the art of converting heat into work by the agency of vapor pressure, which consists in passing a continuously moving circulating fluid from a supply or source of heat to a pressure generator thermally dissociated from said supply or source of heat and containing the working substance, regulating the maximum and minimum temperature of the circulating fluid, regulating the volume of the circulating fluid to maintain a substantially constant volume, applying the circulating fluid to heating the hotter and colder parts of the working substance successively by passing it downward through the pressure generator, and returning the circulating fluid to the circulating fluid supply or source of heat, substantially as described.

45. The improvement in the art of converting heat into work by the agency of vapor pressure, which consists in passing a continuously moving circulating fluid from a supply or source of heat to a pressure generator thermally dissociated from said supply or source of heat and containing the working substance, passing the circulating fluid through uniformly distributed and closely spaced passages first in the steam space and then in the water space of said generator and downward from the hotter to the colder parts of the working substance, and returning the circulating fluid to the circulating fluid supply or source of heat, substantially as described.

46. The improvement in the art of converting heat into work by the agency of vapor pressure, which consists in passing a continuously moving circulating fluid from a supply or source of heat to a pressure generator thermally dissociated from the supply or source of heat and containing the working substance, heating the working substance by the surrender of heat thereto by the circulating fluid, applying the vapor pressure and then exhausting the vapor into a condenser and cooling it by the circulating fluid after the latter is discharged from the pressure generator, and returning the circulating fluid to the circulating fluid supply or source of heat, substantially as described.

47. The improvement in the art of converting heat into work by the agency of vapor pressure which consists in passing a continuously moving circulating fluid from a supply or source of heat to a pressure generator thermally dissociated from the supply or source of heat and containing the working substance, regulating the minimum temperature of the circulating fluid, heating the working substance by the surrender of heat thereto by the circulating fluid, applying the vapor pressure and then exhausting the vapor into a condenser and cooling it by the circulating fluid after the latter is discharged from the pressure generator, and returning the circulating fluid to the circulating fluid supply or source of heat, substantially as described.

48. The improvement in the art of converting heat into work by the agency of vapor pressure, which consists in passing a continuously moving circulating fluid from a supply or source of heat to a pressure generator thermally dissociated from the supply or source of heat and containing the working substance, regulating the maximum and minimum temperature of the circulating fluid, heating the working substance by the surrender of heat thereto by the circulating fluid, applying the vapor pressure and then exhausting the vapor into a condenser and cooling it by the circulating fluid after the latter is discharged from the pressure generator, and returning the circulating fluid to the circulating fluid supply or source of heat, substantially as described.

49. The improvement in the art of convert-

- ing heat into work by the agency of vapor pressure which consists in passing a continuously moving circulating fluid from a supply or source of heat to a pressure generator thermally dissociated from said supply or source of heat and containing the working substance, applying the circulating fluid to heating the hotter and colder parts of the working substance successively by passing it downward through the pressure generator, applying the vapor pressure and then exhausting the vapor into a condenser and cooling it by the circulating fluid after the latter is discharged from the pressure generator, and returning the circulating fluid to the circulating fluid supply or source of heat, substantially as described.
50. The process of generating or increasing vapor pressure by heating a working substance which consists in passing the heating agent downward from the top to the bottom of the working substance and preventing downward circulation of the working substance in the boiler, substantially as described.
51. The process of generating or increasing vapor pressure by heating a working substance, which consists in passing a heat conveying fluid downward in uniformly distributed and closely spaced passages from the top to the bottom of the working substance, substantially as described.
52. The process of generating or increasing vapor pressure by heating a working substance, which consists in passing a heat conveying fluid and the working substance through a pressure generator in opposite currents, the heat conveying fluid passing downward and the working substance upward, and preventing downward circulation of the working substance in the boiler, substantially as described.
53. The process of generating or increasing vapor pressure by heating a working substance, which consists in passing a heat conveying fluid downward through the working substance in uniformly distributed and closely spaced passages extending horizontally through successive layers of the working substance, substantially as described.
54. The process of generating or increasing vapor pressure by heating a working substance, which consists in passing a heat conveying fluid downward through first the steam space and then through the water space in uniformly distributed and closely spaced passages extending horizontally through successive layers of the steam and water or other working substance, substantially as described.
55. The process of condensing or cooling vapor which consists in passing the vapor and cooling fluid through a condenser in opposite directions vertically, the vapor passing downward and the cooling liquid upward through uniformly distributed and closely spaced passages, substantially as described.
56. The process of condensing or cooling

vapor, which consists in passing the vapor and cooling liquid through a condenser in opposite directions vertically, the vapor passing downward from top to bottom of the condenser and the cooling liquid passing upward from bottom to top of the condenser, the passages for the cooling vapor or fluid consisting of uniformly and closely spaced passages extending horizontally through layers of the other substance, substantially as described.

57. The process of condensing or cooling vapor, which consists in passing the vapor through a series of passages immersed in a cooling liquid and circulating said liquid by continuously withdrawing liquid from the top and injecting it upward at different points at the bottom of the liquid with sufficient force to maintain a constant agitation of the surface of the cooling liquid, substantially as described.

58. The process of condensing or cooling a vapor, which consists in passing the vapor through a series of passages immersed in a cooling liquid, circulating said liquid by continuously withdrawing liquid from the top and injecting it upward at different points at the bottom of the liquid with sufficient force to maintain a constant agitation of the surface of the cooling liquid, and maintaining a current of air over the top of the liquid, substantially as described.

59. The combination with a heater, of a pressure generator thermally dissociated from the heater for applying a circulating fluid and means for regulating the minimum temperature of the circulating fluid to heating the working substance, and connections from the heater to the pressure generator for the circulating fluid, substantially as described.

60. The combination with a heater, of a pressure generator thermally dissociated from the heater for applying a circulating fluid to heating the working substance, connections from the heater to the pressure generator for the circulating fluid, and means for regulating the maximum temperature of the circulating fluid, substantially as described.

61. The combination with a heater, of a pressure generator thermally dissociated from the heater for applying a circulating fluid to heating the working substance, connections from the heater to the pressure generator for the circulating fluid, and means for regulating the maximum temperature and speed of the circulating fluid, substantially as described.

62. The combination with a heater, of a pressure generator thermally dissociated from the heater for applying a circulating fluid to heating the working substance, and connections from the heater to the pressure generator and return to heater for the circulating fluid and means for regulating the minimum temperature of the circulating fluid, substantially as described.

63. The combination with a heater, of a pressure generator thermally dissociated

from the heater for applying a circulating fluid to heating the working substance, connections from the heater to the pressure generator and return to heater for the circulating fluid, means for regulating the minimum temperature of the circulating fluid, and a circulating pump, substantially as described.

64. The combination with a heater, of a pressure generator thermally dissociated from the heater for applying a circulating fluid to heating the working substance, connections from the heater to the pressure generator and return to heater for the circulating fluid, and means for regulating the temperature of the circulating fluid, substantially as described.

65. The combination with a heater, of a pressure generator thermally dissociated from the heater for applying a circulating fluid to heating the working substance, connections from the heater to the pressure generator and return to heater for the circulating fluid, and means for regulating the maximum and minimum temperature of the circulating fluid, substantially as described.

66. The combination with a heater, of a pressure generator thermally dissociated from the heater for applying a circulating fluid to heating the working substance, connections from the heater to the pressure generator and return to heater for the circulating fluid, and means for regulating the circulating speed of the circulating fluid, substantially as described.

67. The combination with a heater, of a pressure generator thermally dissociated from the heater for applying a circulating fluid to heating the working substance, connections from the heater to the pressure generator and return to heater for the circulating fluid, and means for regulating the maximum temperature and circulating speed of the circulating fluid, substantially as described.

68. The combination with a heater, of a pressure generator thermally dissociated from the heater for applying a circulating fluid to heating the working substance, connections from the heater to the pressure generator for the circulating fluid, and secondary connections for the circulating fluid cutting out the pressure generator, substantially as described.

69. The combination with a heater, of a pressure generator thermally dissociated from the heater for applying a circulating fluid to heating the working substance, connections from the heater to the pressure generator for the circulating fluid, secondary connections for the circulating fluid cutting out the pressure generator, and means for controlling said secondary connections by the temperature of the circulating fluid, substantially as described.

70. The combination with a heater, of a pressure generator thermally dissociated from the heater for applying a circulating fluid to heating the working substance, connections

from the heater to the pressure generator for the circulating fluid, secondary connections for the circulating fluid cutting out the pressure generator, means for regulating the maximum temperature of the circulating fluid, and means for controlling said secondary connections by the temperature of the circulating fluid, substantially as described.

71. The combination with a heater, of a pressure generator thermally dissociated from the heater for applying a circulating fluid to heating the working substance, connections from the heater to the pressure generator and return to heater for the circulating fluid, and a secondary circulating connection for cutting out the pressure generator, substantially as described.

72. The combination with a heater, of a pressure generator thermally dissociated from the heater for applying a circulating fluid to heating the working substance, connections from the heater to the pressure generator and return to heater for the circulating fluid, a secondary circulating connection for cutting out the pressure generator, and means for controlling said secondary connection by the temperature of the circulating fluid, substantially as described.

73. The combination with a heater, of a pressure generator thermally dissociated from the heater for applying a circulating fluid to heating the working substance, connections from the heater to the pressure generator and return to heater for the circulating fluid, a secondary circulating connection for cutting out the pressure generator including an evaporative tank, and means for controlling said secondary connection by the temperature of the circulating fluid, substantially as described.

74. The combination with a heater, of a pressure generator thermally dissociated from the heater for applying a circulating fluid to heating the working substance, connections from the heater to the pressure generator and return to heater, a circulating fluid supply, and means for regulating the volume of the circulating fluid, substantially as described.

75. The combination with a heater, of a pressure generator thermally dissociated from the heater for applying a circulating fluid to heating the working substance, connections from the heater to the pressure generator and return to heater, an expansion tank on said connections, a supply tank, connections between said supply and expansion tanks, and means for regulating said connections controlled by the circulating fluid in the expansion tank, substantially as described.

76. The combination with a heater, of a pressure generator thermally dissociated from the heater for applying a circulating fluid to heating the working substance, connections from the heater to the pressure generator and return to heater, a circulating fluid supply and means for regulating the volume of circulating fluid, and means for regulating the

temperature of the circulating fluid, substantially as described.

77. The combination with a heater, of a pressure generator thermally dissociated from the heater for applying a circulating fluid to heating the working substance, connections from the heater to the pressure generator and return to heater, a circulating fluid supply and means for regulating the volume of the circulating fluid, and means for regulating the minimum temperature of the circulating fluid, substantially as described.

78. The combination with a heater, of a pressure generator thermally dissociated from the heater for applying a circulating fluid to heating the working substance, connections from the heater to the pressure generator and return to heater, a circulating fluid supply and means for regulating the volume of the circulating fluid, and means for regulating the maximum temperature and speed of the circulating fluid, substantially as described.

79. The combination with a heater, of a pressure generator thermally dissociated from the heater for applying a circulating fluid to heating the working substance, connections from the heater to the pressure generator for the circulating fluid, and means for regulating the volume of working substance, substantially as described.

80. The combination with a heater, of a pressure generator thermally dissociated from the heater for applying a circulating fluid to heating the working substance, connections from the heater to the pressure generator and return to heater for the circulating fluid, a circulating fluid supply, means for regulating the volume of circulating fluid, and means for regulating the volume of working substance, substantially as described.

81. The combination with a heater, of a pressure generator thermally dissociated from the heater for applying a circulating fluid to heating the working substance, connections from the heater to the pressure generator and return to heater for the circulating fluid, means for regulating the temperature of the circulating fluid, a circulating fluid supply, means for regulating the volume of circulating fluid, and means for regulating the volume of working substance, substantially as described.

82. The combination with a heater, of a pressure generator thermally dissociated from the heater for applying a circulating fluid to heating the working substance, connections from the heater to the pressure generator and return to heater for the circulating fluid, means for regulating the maximum temperature and speed of the circulating fluid, a circulating fluid supply, means for regulating the volume of circulating fluid, and means for regulating the volume of working substance, substantially as described.

83. The combination with a heater, of a pressure generator thermally dissociated from the heater and having uniformly distributed

and closely spaced passages extending downward through the working substance, and connections between the heater and said passages at the top of the pressure generator for the circulating fluid, substantially as described.

84. The combination with a heater, of a pressure generator thermally dissociated from the heater and having continuous uniformly distributed and closely spaced passages extending horizontally and downward through successive layers of the working substance, and connections between the heater and said passages at the top of the pressure generator for the circulating fluid, substantially as described.

85. The combination with a heater, of a pressure generator thermally dissociated from the heater and having continuous uniformly distributed and closely spaced passages extending horizontally and downward through successive layers of the steam space and working substance, and connections between the heater and said passages at the top of the pressure generator for the circulating fluid, substantially as described.

86. The combination with a heater, of a pressure generator thermally dissociated from the heater and having small uniformly distributed and closely spaced continuous passages extending horizontally and downward through successive layers of the steam space and working substance, and connections between the heater and said passages at the top of the pressure generator for the circulating fluid, substantially as described.

87. The combination with a heater, of a pressure generator thermally dissociated from the heater and having passages extending downward through the working substance, connections between the heater and said passages at the top of the pressure generator for the circulating fluid, and means for regulating the temperature of the circulating fluid, substantially as described.

88. The combination with a heater, of a pressure generator thermally dissociated from the heater and having passages extending downward through the working substance, connections between the heater and said passages at the top of the pressure generator for the circulating fluid, and means for regulating the minimum temperature of the circulating fluid, substantially as described.

89. The combination with a heater, of a pressure generator thermally dissociated from the heater and having passages extending downward through the working substance, connections between the heater and said passages at the top of the pressure generator for the circulating fluid, and means for regulating the maximum and minimum temperature of the circulating fluid, substantially as described.

90. The combination with a heater, of a pressure generator thermally dissociated from the heater and having passages extending

5 downward through the working substance, connections between the heater and said passages at the top of the pressure generator for the circulating fluid, and means for regulating the speed of the circulating fluid, substantially as described.

91. The combination with a heater, of a pressure generator thermally dissociated from the heater and having passages extending 10 downward through the working substance, connections between the heater and said passages at the top of the pressure generator for the circulating fluid, and means for regulating the maximum temperature and speed of 15 the circulating fluid, substantially as described.

92. The combination with a heater, of a pressure generator thermally dissociated from the heater for applying a circulating fluid to 20 heating the working substance, connections from the heater to the pressure generator for the circulating fluid, means for applying the vapor pressure and a working substance condenser for the pressure generator, connections 25 between the pressure generator and condenser for the circulating fluid, wherein further heat is abstracted from the circulating fluid and the fluid then applied to condensing the working substance, and connections for 30 the return of the circulating fluid from the condenser to the heater, substantially as described.

93. The combination with a heater, of a pressure generator thermally dissociated from 35 the heater for applying a circulating fluid to heating the working substance, connections from the heater to the pressure generator for the circulating fluid, a thermostat on said connections, and means controlled by said 40 thermostat for regulating the temperature of the circulating fluid, substantially as described.

94. The combination with a heater, of a pressure generator thermally dissociated from 45 the heater for applying a circulating fluid to heating the working substance, connections from the heater to the pressure generator for the circulating fluid, a thermostat on said connections, secondary connections for the 50 circulating fluid cutting out the pressure generator, and means controlled by said thermostat for controlling said secondary connections, substantially as described.

95. The combination with a heater, of a 55 pressure generator thermally dissociated from the heater for applying a circulating fluid to heating the working substance, connections from the heater to the pressure generator for the circulating fluid, a thermostat controlled 60 by the temperature of the circulating fluid, and means controlled by said thermostat for regulating the minimum temperature of the circulating fluid, substantially as described.

96. The combination with a heater, of a 65 pressure generator thermally dissociated from the heater for applying a circulating fluid to heating the working substance, connections

from the heater to the pressure generator and return to heater for the circulating fluid, a thermostat on said connections between the 70 heater and pressure generator, and means controlled by said thermostat for regulating the temperature of the circulating fluid, substantially as described.

97. The combination with a heater, of a 75 pressure generator thermally dissociated from the heater for applying a circulating fluid to heating the working substance, connections from the heater to the pressure generator and return to heater for the circulating fluid, 80 thermostats on said connections on each side of the pressure generator, and means controlled by said thermostats for regulating the maximum and minimum temperature of the circulating fluid, substantially as described. 85

98. The combination with a heater, of a pressure generator thermally dissociated from the heater for applying a circulating fluid to heating the working substance, connections from the heater to the pressure generator and 90 return to heater for the circulating fluid, thermostats on said connections on each side of the pressure generator, and means controlled by said thermostats for regulating the maximum temperature and speed of the 95 circulating fluid, substantially as described.

99. The combination with a heater, of a pressure generator thermally dissociated from the heater for applying a circulating fluid to heating the working substance, connections 100 from the heater to the pressure generator for the circulating fluid, a circulating pump, a by-pass for the circulating fluid about said circulating pump, a valve controlling said by-pass and means for controlling said 105 valve in accordance with the temperature of the circulating fluid, substantially as described.

100. A boiler having uniformly distributed and closely spaced passages for a heating 110 agent extending from the top downward through the space for the working substance, substantially as described.

101. A boiler having uniformly distributed and closely spaced passages through it from 115 top to bottom for a heating agent, and from bottom to top for the working substance, substantially as described.

102. A boiler having an inlet at or near the top and outlet at or near the bottom for a 120 heating agent, and an inlet at or near the bottom and outlet at or near the top for the working substance, and uniformly distributed and closely spaced passages connecting the respective inlets and outlets, substantially as 125 described.

103. A boiler having small uniformly distributed and closely spaced passages for a heating agent extending downward from the top through the space for the working sub- 130 stance, substantially as described.

104. A boiler having uniformly distributed and closely spaced passages for a heating agent extending horizontally and downward

through successive parts and from the top toward the bottom of the space for the working substance, substantially as described.

105. A boiler having uniformly distributed and closely spaced passages for a heating agent extending horizontally and downward through successive parts of the steam space and from the top toward the bottom of the space for the working substance, substantially as described.

106. A boiler having small uniformly distributed and closely spaced passages for a heating agent extending horizontally and downward through successive parts and from the top toward the bottom of the space for the working substance, substantially as described.

107. A boiler having small closely spaced passages for a heating agent extending horizontally and downward through successive parts and from the top toward the bottom of the space for the working substance, and sheets of wire gauze between and in contact with the horizontal layers of passages, substantially as described.

108. A boiler having an inlet and outlet for a heat conveying circulating fluid and an inlet and outlet for working substance, and uniformly distributed and closely spaced passages for the circulating fluid within the space for the working substance, substantially as described.

109. A boiler having an inlet and outlet for a heat conveying circulating fluid and an inlet and outlet for working substance, and uniformly distributed and closely spaced passages for the circulating fluid through both the steam space and water space, substantially as described.

110. A boiler having an inlet and outlet for a heat conveying circulating fluid, and an inlet and outlet for working substance, and uniformly distributed and closely spaced passages for the circulating fluid extending horizontally through successive vertical parts of the space for the working substance, substantially as described.

111. A boiler having an inlet and outlet for a heat conveying circulating fluid, and an inlet and outlet for working substance, and small uniformly distributed and closely spaced passages for the circulating fluid extending horizontally through successive vertical parts of the space for the working substance, substantially as described.

112. A boiler having an inlet and outlet for a heat conveying circulating fluid, and an inlet and outlet for working substance, and small uniformly distributed and closely spaced passages for the circulating fluid extending horizontally through successive vertical parts of both the steam space and water space, substantially as described.

113. A boiler having an inlet and outlet for a heat conveying circulating fluid, and an inlet and outlet for working substance, passages for the circulating fluid within the space

for the working substance, and a blow-off valve for the liquid working substance controlled by the boiler pressure, substantially as described.

114. An apparatus for the transfer of heat from one fluid to another having uniformly distributed and closely spaced passages for the fluid from which heat is to be transferred extending from the top downward through the space for the fluid to which heat is to be transferred, substantially as described.

115. The combination with a casing having an inlet at or near the top and outlet at or near the bottom for fluid from which heat is to be transferred, an inlet at or near the bottom and outlet at or near the top for fluid to which heat is to be transferred from the first mentioned fluid, and uniformly distributed and closely spaced passages for one of the fluids connecting its respective inlet and outlet and extending through the space for the other fluid, substantially as described.

116. The combination with casing p , having a connection at top and bottom, of casing B inside said casing, having a connection at top and bottom, uniformly distributed and closely spaced tubes extending transversely through said casing B, and partitions 17 dividing said casing p outside casing B into horizontal chambers, substantially as described.

117. The combination with casing p , having a connection at top and bottom, of casing B inside said casing, having a connection top and bottom, small closely spaced tubes n extending transversely through said casing B, and partitions 17 dividing said casing p outside casing B into horizontal chambers, substantially as described.

118. The combination with a casing having a fluid connection at opposite ends, of small closely spaced tubes extending transversely through said casing, chambers arranged longitudinally of said casing and communicating with the opposite ends of series of tubes, and a fluid connection with the end chambers, substantially as described.

119. The combination with an open tank having a perforated bottom, of passages through said tank for fluid to be cooled, and a circulating pump for withdrawing the cooling liquid from the top and injecting it through the perforated bottom of the tank, substantially as described.

120. The combination with an open tank having a perforated top and bottom, of passages through said tank for fluid to be cooled, and a circulating pump for withdrawing the cooling liquid from the top and injecting it through the perforated bottom of the tank, substantially as described.

121. The combination with an open tank having a perforated top and bottom, of passages through said tank for fluid to be cooled, a circulating pump for withdrawing the cooling liquid from the top and injecting it through the perforated bottom of the tank,

and means for maintaining an air blast over the top of the tank, substantially as described.

122. The combination with a heater, of a pressure generator thermally dissociated from the heater for applying a circulating fluid to heating the working substance, connections from the heater to the pressure generator and return to heater for the circulating fluid, an expansion engine having cylinder jackets, and connections for circulating a part of the

circulating fluid through said jackets, substantially as described.

In testimony whereof I have hereunto set my hand in the presence of two subscribing witnesses.

A. M. WELLINGTON.

Witnesses:

T. F. KEHOE,
C. J. SAWYER.

Correction in Letters Patent No. 549,981.

It is hereby certified that in Letters Patent No. 549,981, granted November 19, 1895, upon the application of Arthur M. Wellington, of New York, N. Y., for an improvement in the "Art of and Apparatus for Converting Heat into Work by Agency of Vapor Pressure," an error appears in the printed specification requiring correction as follows: On page 28, lines 102-103, the clause "and means for regulating the minimum temperature of the circulating fluid," should be stricken out and inserted before the word "substantially," line 106 as now numbered, same page; and that the said Letters Patent should be read with this correction therein that the same may conform to the record of the case in the Patent Office.

Signed, countersigned, and sealed this 17th day of December, A. D. 1895.

[SEAL.]

JNO. M. REYNOLDS,
Assistant Secretary of the Interior.

Countersigned:

JOHN S. SEYMOUR,
Commissioner of Patents.
